UNITED STATES PATENT OFFICE.

DAVID S. HULFISH, OF TORONTO, ONTARIO, CANADA, ASSIGNOR TO CANADIAN INDEPENDENT TELEPHONE COMPANY, LIMITED, OF TORONTO, CANADA, A CORPORATION OF CANADA.

TELEPHONY.

1,220,228.

Specification of Letters Patent.

Patented Mar. 27, 1917.

Original application filed May 13, 1912, Serial No. 696,902. Renewed August 7, 1915, Serial No. 44,292. Divided and this application filed September 30, 1912. Serial No. 723,228.

To all whom it may concern:

Be it known that I, DAVID S. HULFISH, engineer, a citizen of the United States of America, residing at Toronto, in the county of York and Province of Ontario, Canada, have invented certain new and useful Improvements in Telephony, of which the following is a specification and a description of the manner and process of constructing and using the same, intended to be in such full, clear, concise, and exact terms as to enable any person skilled in the art to make and use the same.

My invention relates to telephone systems in general and to the application of methods and apparatus for telephone switching in central offices of telephone exchanges, and this application is a division of my prior application Serial No. 696,902, filed May 13, 1912, and renewed as Serial No. 44,292, Aug. 7, 1915. In some of its details, it is particularly adapted to systems of the "Lorimer" type of automatic telephone devices and I have shown it in this application applied specifically to a system of circuits for the "Lorimer" type of automatic apparatus with suggestions from time to time as to the general application of certain features of my invention to the general art of telephony in central offices whether automatic or manual.

My invention has for its objects the following:

(B) A method of calling among lines entering an automatic telephone exchange whereby the order of answering contemporaneously existing calls may be varied from time to time.

(C) A combined sequence switch and division starter.

(D) A system of test circuits for determining the busy or idle condition of a tested circuit, whereby the tested circuit may have either of two potentials impressed upon it during its busy condition and the testing circuits will reject it if it bears either potential.

(F) An improved system for testing a telephone line for busy or idle condition, and the subsequent adjustment of automatic switches in accordance with the result of the test, including a locking relay for recording the result of the transient test, the

relay being held locked for a sufficient time for reliable operation of the automatic switches requiring control subsequent to the test and independently upon the test.

(G) An improved system of commutators and associated circuits for ringing code ringing upon party lines in an automatic telephone exchange.

(H) An improved system of controlling circuits for an automatic telephone connective apparatus, controlled by the two telephones of the connection, and controlling the release of the connection at the will of either of the telephone users.

(K) A system of lamp signals for an automatic telephone exchange in which a different order of signals is produced when the line called for is busy as compared with the signals produced when the line called for is tested and found idle; also, an improved signal in a set of lamps whereby two lamps each having a definite meaning when burning alone may be caused to burn simultaneously to express a third and independent meaning.

(M) An improved timer device or slow relay.

(N) An improved timer device having alarm points and automatic release points and adapted to close the alarm points first and to close the automatic release points after a delay subsequent to the closing of the alarm points whereby an abnormal action is at first indicated by an alarm and later is relieved automatically and the apparatus restored.

(P) An improved circuit and means in connection with an automatic lamp alarm and release device whereby the attendant in charge of an automatic exchange may disable either the automatic release functions of the telephone office or the lamp alarm functions of the telephone office, but not both.

(Q) An improved multiple brush, for an automatic switch, engaging a plurality of contact points on the same level and closing through them a plurality of simultaneous circuits.

(R) A brush arrangement by which two independent multiple brushes act upon the same level of contact points and close simultaneous and independent circuits through

the same level of points, each circuit being closed twice in a single cycle of the switch, one closure for each multiple brush.

(SA) A system of mutual circuits between two automatic switches, such that the return of either to normal will return the other to normal also.

(SB) A system of main circuits and of auxiliary circuits in an automatic exchange, such that the control of an automatic switch normally by a line and its telephone is substituted by a central office auxiliary circuit in case the switch has no connected line.

(SC) A system of circuits by which the pilot switch when at normal restores other switches to normal, namely, the primary connector and the signal controller.

(SD) A system of driving devices and circuits for a timing device whereby one timer may be driven at different speeds at different times.

(SE) I provide a division starter with a timing device whereby a second division will be started in case the first does not respond promptly.

(SF) A novel disabling circuit for a division starter when all divisions are busy.

(SG) A method of using duplicated devices or electrical circuits having a common destination by using them in order of rotation.

(SH) A method of using a group of electrical circuits having a common destination by dividing them into two small groups, one small group used in rotation and the remaining small group used as an overflow group and used in numerical order of precedence.

(SM) A system and method of metering calls in which a call is recorded upon the meter of the calling line only as a result of the response of the called line.

(SN) A detail of metering system for general application in telephone exchanges by which certain lines may be designated as "free service" lines and calls terminating upon these lines will not register upon the meter of the calling line when the "free service" line responds.

(SP) A system for seizing a busy line with disregard of the guarding condition.

(SQ) An improved telephone for a subscriber's station suitable for a party line having features of reverting call ringing.

(SR) An improved party line telephone with an interference device.

In the drawings which accompany and form a part of this specification:

Figure 1 shows the circuits of the primary connector or A-switch.

Fig. 2 shows the circuits of the pilot switch and thousands or ringing register.

Fig. 3 shows the circuits of the relays, commutators, division timer and sundry other apparatus.

Fig. 4 shows the circuits of the signal controller. 65

Fig. 5 shows the circuits of the interconnector or trunk selector.

Fig. 6 shows the circuits of the secondary connector or B-switch. 70

Fig. 7 shows the circuits of the line relays constituting the decimal indicator.

Fig. 8 shows the circuits of the decimal controller.

Fig. 9 shows the circuits of the division starter which is also the permutation controller for the line relays or decimal indicator. 75

Fig. 10 shows the circuits of a telephone for a line having but one telephone. 80

Fig. 11 shows a simplified diagram of the circuits for conversation and for release under subscribers' control.

Fig. 12 shows the circuits of the rotational busy test. 85

Figs. 13, 14 and 15 show details of "free meter lines".

Fig. 16 shows the circuits of a telephone for a party line.

Fig. 17 shows a party line telephone having interference features for party-line. 90

In the figures, numerals smaller than 100 are not strictly reference labels within the ordinary meaning of the term; they are numerals indicating the order or relation of the parts adjacent to which they are found, or to which they directly pertain, as indicating the order of contact points in a row, or the order of rows in a contact bank; for example, the numerals 1-to-44 in Fig. 2 are stamped upon the apparatus as built and used, and form a part of the apparatus illustrated by the drawing. Reference numerals 101 to 199 have been reserved for conductors entering the pilot switch, 200 to 399 for apparatus parts, and 400 and higher for miscellaneous conductors. Like numerals refer to like parts throughout the several figures. 95

The switches.

The switches are of three types, called the cylinder type, the register type and the commutator type.

A switch of the cylinder type is illustrated in Fig. 4. The horizontal rows of small circles represent the fixed contact points projecting from the developed inner surface of an annular casting of insulating material; upon these contact points there move horizontally from left to right a set of brushes, shown in the figure as small flat parallelograms resting upon the points of the first vertical set of points. A controlling magnet or clutch magnet 213 has an armature adapted to engage a notched disk to restrain the disk from turning. The disk is attached to the brushes of the cylinder switch. When the clutch magnet is charged by current 115

110

115

120

125

passing through it, its armature is withdrawn from the notched disk and the disk is permitted or caused to revolve, carrying with it the brushes of the associated cylinder. The disk (and therefore the brushes of the switch) may stop only in positions corresponding to notches in the periphery of the disk, and these notches therefore represent the only possible stop positions of the 10 brushes of the switch.

In the primary connector of Fig. 1 the stop positions of the brushes are all but one in the first quadrant of revolution, as indicated by the location of eleven notches in the 15 clutch disk.

In the pilot switch of Fig. 2 there are 20 fourteen stop positions, irregularly distributed. The vertical sets of contacts of the cylinder are numbered horizontally 1-to-44, the stop positions of the brushes are numbered in the line above, 1-to-14, each number appearing twice, over each of the two adjacent sets of points occupied by the main set of pilot brushes in each of the indicated 25 stop positions; the brushes normally when not in use upon No. 1 stop position, or contact sets 1 and 2. The horizontal rows of cylinder points are numbered 1-to-14 from top to bottom, at the left.

30 The pilot switch of Fig. 2 has also a set of auxiliary brushes, three pairs on 3rd, 7th, and 9th levels, respectively resting normally on points of 34th and 35th sets and moving with the main brushes. The main brushes 35 of the 7th level are connected by a wire to the auxiliary brushes of the same level.

In the signal transmitter controller of Fig. 4 the clutch disk has four notches. The disk is geared to the brushes in the ratio of 40 one revolution of the disk for two revolutions of the brushes. The complete cycle of operations of the switch is effected in two complete revolutions of the brushes, or one revolution of the disk. The stop positioner 45 of the brushes are: normal position on contact set No. 1 first stop position on contact set No. 43 just before the end of the first revolution; second stop position on contact set No. 1; third stop position on contact set No. 50 43 just before the end of the second revolution.

The interconnector of Fig. 5 and the secondary connector of Fig. 6 are switches similar to that of Fig. 1. The division starter 55 of Fig. 9 is a switch similar to that of Fig. 2 but with a different distribution of stop notches, without a register, and with a single set of brushes.

In this specification, a contact point in a 60 cylinder switch (or in a register bank) is identified by giving its vertical row, counting from the left and its position in the row counting from the top, thus; 1X1, upper left point of any bank, pilot 23X14, the pilot

point, middle of bottom row of bank, connected to conductor 105. When two points are engaged by two connected brushes, the points are indicated by a hyphen connection, thus: pilot points 1X13-12 where the engaged points are in the same vertical row; 70 or pilot points 27X3-28X3, pilot points 39X7-7X7, where the engaged points are not in the same vertical row.

A switch of the register type is illustrated in Fig. 1, at the top. The arcs of small circles represent rows of fixed contact points, upon which move the brushes shown as small rectangles upon set No. 0 of the points. The brushes are carried by the ratchet, which is under spring tension against the pallet, 75 and which is permitted to move step-by-step under control of the register magnet 214. This register complete, is carried by the mechanism carrying the cylinder brushes to which the register parts are wired. It is 80 restored to normal position after having been operated, by mechanical devices which restore it during the second quadrant of revolution of the clutch disk.

The ringing register of Fig. 2 is in fixed 85 position, but is located adjacent to an associated cylinder switch, and is restored to normal by the return of the adjacent cylinder switch, such as the pilot switch of Fig. 2. The brushes of the register are reversed, 90 moving from right to left.

The registers of Figs. 5 and 6 are similar to that of Fig. 1 and are similarly restored.

A switch of the commutator type is illustrated in Fig. 8, the decimal register controller. The developed commutator ring of long segment 232 and fifty smaller segments, with its associated brushes, conductors, relay and clutch, form the decimal register controller as a whole, whose function it is to 100 operate the decimal register of a started division to assist in the identification and seizure of the calling line.

There is one decimal register controller for each switchboard section or group of 110 divisions, one such controller thus serving all of a group of lines and controlling the decimal registers of all the corresponding group of connective divisions.

The decimal register controller brushes 115 are equipped with a directly acting clutch, which starts its associated brushes when the clutch magnet is charged and stops them when the clutch magnet is discharged and the dog of the clutch drops into the next 120 notch of the clutch disk. The disk has four notches, but as the two brushes are duplicates and the switch accomplishes its electrical cycle in one-half revolution, there result from the four notches but two stop positions, first with a brush upon the forty-sixth small segment, 230, and second with the same brush upon the fiftieth or last small

segment, 231, the companion brush in each instance being upon the long segment 232.

The switch of Fig. 9 is the division starter and line-sequence controller. The pilot-
5 clutch magnets of the connective divisions when normal are charged only through the starter. The clutch magnet of the first connective division is shown at 215 in Fig. 2, being connected to wire 121, which is shown
10 attached to cylinder point 3X6 in Fig. 9; the corresponding wire of a second division is shown attached to cylinder point 7X6 in Fig. 9. The division of Fig. 2 is further associated with Fig. 9 by the wire 128 shown
15 attached to cylinder point 3X3 in Fig. 9; the corresponding wire of a second division is shown attached to cylinder point 7X3 in Fig. 9. These two wires upon cylinder points 7X6 and 7X3 in Fig. 9 are illustrative of a second complete division such as shown in
20 Figs. 1, 2, 4, 5, 6 and parts of Fig. 3. The starter is sole per group of divisions, (say six to twelve) and per associated group of lines (say one hundred).

25 *The exclusive line telephone.*

The automatic substation telephone comprises the usual items of a telephone set, and in addition an automatic call sender. The 30 circuits for an exclusive-line telephone are shown in Fig. 10.

Grounded brushes, 240, of which four are shown, are adjustable by projecting buttons moved by the telephone user according to indicators 35 to place ground upon one pin in each segment (about a quadrant, as drawn) of a circle of pins 241, which contains several such segments, and upon which a conducting arm 242 rides.

40 The means for propelling the arm 242 over its circle of pins comprises a main spring, a crank for winding the main spring, and an electric escapement controlled by the magnet 248. The escapement permits the 45 arm to move in steps, forty-three steps being required to complete one revolution. The electric escapement is ineffective to make the first step, the first step being made mechanically, preferably by the crank which winds 50 up the main spring, the electric escapement then being effective when properly controlled to make the remaining forty-two steps.

The devices of the central office are 55 adapted to send forty-two impulses for the control of the call-sender escapement, forty-one from the signal controller and one from commutator No. 8.

To set the signal transmitter to effect connection with a desired telephone substation, the indicator buttons are set to the directory number of that substation by moving the buttons independently to positions in which they will indicate the desired directory num-

ber. The wires from the first two indicator 65 points of each set to the contact pins in the circle engaged by the arm 242 are shown in the diagram, Fig. 10. The remaining points are connected in corresponding manner, except the last or tenth point, (directory number "9") which is left unconnected. Contact arm 242 normally engages the point 243 and thus normally holds the talking bridge subject to control by the hook switch 246. Connection from the first conductor of the 75 line 421, to the arm 242 is moved forward mechanically one step by the operation of starting a call, it engages a contact pin 244 which is connected directly to earth or through a return wire to minus battery. 80

A switch, 247, composed of a pair of contact springs, is adapted when closed, to complete the circuit for the stepping magnet 248 from the second conductor of the line 422, to earth. The springs of the switch 247 85 normally are disengaged from each other but are forced into engagement by means of a cam lever 249 moved by a cam disk 239 secured to the shaft of the contact arm 242.

A notch in the cam disk 239 permits the 90 springs of the switch 247 to move the arm 249 and to disengage themselves when the arm 242 stands in the normal position, or in connection with pin 243. When the arm 242 is moved from its normal position, by 95 the action of starting the call, the cam disk 239 operates the lever 249 to close the switch 247, the disk 239 then preserving the closed condition of the switch 247 until the arm 242 completes its revolution and resumes its 100 engagement with the pin 243.

The lines entering a central office are divided into groups of, say, one hundred lines per group, and the automatic equipment of the central office is for the most part divided 105 also, each group of apparatus serving a group of telephone lines; such a group of apparatus is called a switchboard section, or simply a "section."

In each such section the switches for the 110 most part are grouped into groups called connective divisions, each group or division constituting a connective unit analogous to a switching cord-pair equipment in a manual telephone switchboard.

115 The automatic switches which make up a connective unit or connective division in the figures of this application are: primary connector or A-line switch, Fig. 1; pilot switch and thousands or ringing register, Fig. 2; 120 relays, timer, lamps, condensers, resistances, Fig. 3, signal controller, Fig. 4; interconnector, Fig. 5; secondary connector or B-line switch, Fig. 6.

The automatic switches of a section, common to all divisions, are:—decimal register controller, Fig. 8; division starter, Fig. 9.

The total process of connecting two lines

automatically in such an office comprises: (1) A primary adjustment by which a connective division is associated with a calling line. (2) Selective adjustments by which

6 circuit-selecting switches are adjusted to select such circuits as will result ultimately in associating the connective division with the line desired by the calling line and indicated by the preliminary manual adjustment of its 10 call sender. (3) Test and preliminary ring by which the line selected is rung upon if not found engaged. (4) Repeated ring until the call is answered. (5) Maintenance of a 15 condition for conversation after the ring is answered and release by subscriber's control. (6) Restoration automatically of all parts of the connective division after conversation and release. (7) Throughout all of these 20 operations the connective division is supervised by a system of lamp signals which operate to announce normal action, and abnormal action, if any. (8) The division is further guarded by automatically operative restoring or normalizing circuits and devices 25 which act to restore it to normal condition for further service in event of abnormal operation. (9) Special service requirements compel some specialization of apparatus or 30 circuits, or both.

30 Early forms of decimal indicators, constructed for one hundred lines, have comprised a rotating device capable of being stopped in one hundred different positions, each position corresponding to a line served 35 by the device. When thus stopped by a calling line, the decimal indicator identified the calling line by placing an electrical potential upon two identified and line-identifying wires in two sets, each set comprising ten 40 wires and one wire being identified in each set. These sets were the decimal set and the unit set. By the wire identified in the decimal set, the tens digit of the calling line was made known, and by the wire identified 45 in the units set, the units digit of the calling line was made known. The decimal indicator comprises one hundred line-signal or line indicating relays, each relay having two pairs of contact points, one pair being 50 connected properly to place an identifying electrical potential upon the proper wire in the tens set corresponding to the line of that relay and the other pair of contact points being similarly connected to place an identifying 55 potential upon the proper wire in the units set. The charging of a line relay thus identifies the calling line by identifying two conductors which in turn identify the line, the subsequent selection of the line 60 being accomplished by a connective division upon fundamental principles heretofore used. Associated with each line relay is a cut-off relay and associated with each units wire is an additional signal relay, or se-

quence relay, making a bank of two hundred 65 ten relays in all required for a completely equipped decimal indicator for one hundred lines.

(B) In the rotating decimal indicator the calling lines were served on either of the two 70 principles of selection, dependent upon the circuits used. The first principle was that the lines should be served in rotation as they might call, the search being made in numerical order and each calling line being assigned 75 to a connective division before the rotating decimal indicator proceeded further in its search, the rotating device being held motionless upon a calling line so long as all connective divisions were engaged. The second plan was that lines should be served as in the first plan until all connective divisions became engaged, after which the rotating device would not stop upon any calling 80 line until after a connective division had become idle and in condition to serve the line. The second plan therefore left to a matter of chance the selection of one calling line from several calling lines, when, all connective divisions having been busy, one connective division 85 was released and made available for serving one of the several calling lines. In my improved system, the lines are arranged 90 in a series circuit in an order whereby certain lines have precedence over all others 95 and are served in precedence when the connective divisions are insufficient to serve all calling lines. To guard against immoderate use of the connective divisions by certain favored lines to the exclusion of lines less 100 favorably located upon the series circuit, I provide a permutation device which from time to time changes the order of precedence 105 of the lines and thereby distributes the service of a group of connective divisions more uniformly among the lines served by that group.

(C) I accomplish the permuting requirements above recited by utilizing the cylinder switch of the division starter. In the 110 drawings which accompany this specification, I show the lowest six levels of the division starter cylinder thus utilized.

(D) The full economy of a trunk circuit, having a minimum number of conductors, 115 in an automatic telephone exchange can be realized at times only by using some one conductor for more than one function in the progress of setting up, maintaining, and disrupting a connection. I have met a requirement of this nature by using the same conductor for the operation of the clutch of a test switch and for a busy-test conductor offering a condition suitable for electrical test to determine whether the distant switch 120 is in normal position or otherwise. As the conductor thus used will vary its potential 125 from time to time as operating currents do

or do not pass over it to control the distant switch, it is necessary for the testing circuit at any moment to show that the distant switch is engaged, regardless of the variations of potential upon the conductor serving the double purpose of switch control and busy test. I have provided three different potentials in the automatic central office of which two may be applied to the conductor in question for such switch control, the third being applied for test purposes the test-and-control conductor being so associated with apparatus that it will be entirely isolated only when the distant switch is idle, so that no current will flow from the testing devices to the wire in question if the switch be idle but current will flow from the test devices to either of the two operating potentials if the switch be busy. By the flow of current from the test device, it may be known that the distant switch is busy and the test device may be controlled in accordance therewith.

(F) In the automatic telephone system shown in the accompanying drawings it is necessary to adjust the selecting switches to variant positions according as selected line is found to test engaged or free. If the tested line be found engaged, the pilot switch is advanced immediately after the test, but if the tested line be found free, the signal controller is advanced immediately after the test and the pilot switch is advanced subsequently.

To provide ample time for moving these switches to their position of adjustment in accordance with the result of the test upon the selected line, I provide a locking test relay which by locking will record the result of the test indefinitely or for such a length of time as may be required for the adjustment of the selective switches involved.

To insure the maintenance of the locking circuit for a sufficient time to move the pilot switch, I carry the locking circuit through the pilot switch.

(G) In my improved system of commutators for ringing in code manner upon party lines, I provide commutators each of which produces a group of impulses arranged in a code manner, and I cause these commutators to repeat each group of impulses as frequently as feasible. In order that the code ring upon a telephone line may be repeated less frequently, I provide an auxiliary commutator. My auxiliary commutator is so designed and so connected in the circuits of the ringing devices that it permits the operation from time to time of one group of the code impulses, withholding the operation of the intervening repetitions of the group. I do this by connecting in series in a single circuit a fast and a slow commutator, and so associating the commutators that the slow commutator will be closed during one cycle

of the fast commutator and be open for a predetermined number of succeeding cycles.

I provide also in the pilot switch two ringing positions. In the first ringing position, the fast commutators are effective to ring at 70 all times; and I provide means for permitting the pilot switch to remain in this position during one and one only cycle of the fast commutators, thus attaining a single initial code ring, with a minimum of 75, delay before such initial ring.

(H) In my improved system of controlling circuits I provide four stop positions for the pilot switch in which the further movement of the pilot switch, and therefore 80 the entire command of the connection, is under control of either of the two connected telephones. In the first position, pilot stop No. 9, the lifting of either telephone from the hook will advance the pilot. The next position, pilot stop No. 10 is held when the A-line telephone is off the hook and the B-line telephone is on the hook. The third position, pilot stop No. 11 is held when the A-line telephone is on the hook 90 and the B-line telephone is off the hook. The fourth position, pilot stop No. 12 is held when both telephones are off the hook and the pilot switch is advanced by hanging up either telephone. Advantages are 95 formed in the control of the visual signals indicating the condition of the connection, and advantages are found in the complete system of control by which connection at all times is under complete control by either 100 telephone without any operation other than the usual hook-switch operations common in either automatic or manual telephone usage.

(K) In association with a connective division, I provide a set of signal lamps and 105 a system of lamp signals by which the condition of the connective division may be known. These lamps are mounted prominently upon the frames supporting the switches and in such manner that an attendant seated in a supervising position may see from the one view point all the lamps of a central office or of his portion of a central office. In connection with this plan, my system of lamp signals is such that 110 the attendant by watching the lamp signals may know to a very considerable degree the progress made by any call which is received by the central office apparatus. I provide three lamps and a normal call normally 115 handled by the central office apparatus will produce illuminations of these lamps, or two of them, in a predetermined order and of predetermined durations which may be recognized visually by the attendant as indicating a connective division and a telephone user both acting in a normal manner.

While a call terminating upon a line previously engaged (the call therefore being 120 defeated because of the guard or busy-test 125

condition upon the called line) may be considered in some ways as a normal call, I provide such details in my system of lamp signals and circuits that the sequence of signals produced when calling an engaged line is different from the sequence of signals produced when calling an idle line. By this detail of improvement, an attendant watching the lamps of a distant operating division, 10 may know whether the call is terminated upon an idle or a busy selected line.

I provide also a signal which is displayed when the subscriber upon the B-line of the connection lifts his receiver before the lifting 15 of the receiver upon the A-line. This is a condition having a peculiar interest in an automatic exchange of the character herein described. My improved signal for this condition also has a peculiar interest in that 20 for the display of this signal I cause to glow simultaneously two lamps, neither of which indicates when glowing alone any part of the condition indicated when both glow simultaneously.

25 Two lamps are provided to indicate normal operation of switches and a third lamp is provided as an alarm lamp indicating an abnormal delay in the operation of the switches whether upon the part of central office devices or upon the part of telephone users.

(M) For the detection of automatic switches operating abnormally, I provide a timing device which is the equivalent of a slowly acting relay, the device being so adjusted that it will become operative as soon as an automatic switch becomes inoperative and that it will become operative when the automatic switch reaches its normal position or any predetermined position. The relay contacts may be connected in an alarm circuit or in a circuit to restore the automatic switch to normal or both. The speed of operation of the slow relay or timing device 45 then may be adjusted to give the automatic switch sufficient interval to operate in normal manner before the timing device closes its contact points. By means of such a device, an automatic switch may be brought to the attention of an attendant through the alarm when the switch is not operating in normal manner or at normal speed; or, on the other hand, an automatic switch may be caused always to return to normal in readiness for further service, in case it has not operated in normal manner and within a predetermined time limit.

(N) I combine in one device the functions 60 of an alarm timer and a release timer.

I provide, in my improved timer, two pairs of electrical contact springs, and I provide a moving striker driven step by step toward the springs. I so place the springs with reference to the striker that the striker engages and closes the first pair of springs

upon a predetermined step, and I so place the second pair of springs that upon the next succeeding or some predetermined succeeding step, the striker will engage and close the second pair of springs either directly or by moving the first pair of springs or contact members to engage the second pair.

I thus cause my improved timer to close two circuits, each having a predetermined delay after the beginning of operation of the timer, one circuit having a greater delay than the other if desired. It is obvious that both circuits may be closed simultaneously if desired as an alternative method of operation.

By means of the delay of the second closing after the first, I am enabled so to connect my timer contact points, that an abnormal action of an automatic switch is first 85 indicated by an alarm, and later is relieved automatically by restoration of the switch, or I may provide an automatic release and cause an alarm later if the automatic release has not been effective.

(P) When an automatic exchange is fully supervised, as in the busy hours of the day, it may be desired that every case of abnormal action be studied by the attendant and that no automatic releasing be permitted, all 90 abnormal switches being released and restored manually by the attendant; in such a case it is desirable that the automatic release circuits of the timers be disabled. When the automatic exchange is unattended 100 as at night and on holidays, the alarm circuits associated with automatic releasing devices have no practical value and may be disabled, leaving the normalizing of the automatic switches wholly to the care of the 105 timer-controlled releasing circuits. It is obvious, however, that the exchange should not be left at any time without either alarm or release circuits operative.

I provide in connection with my improved lamp-and-release a switch having two positions, in one position disabling the releasing circuits of the entire exchange, in the other position disabling the lamp-alarm circuits of the entire exchange. I provide such circuits for the alarm that they may be connected to a single bus wire through the night switch. In like manner I provide such a circuit for the release circuits of all the timer devices that they may be collected upon a 120 single bus wire through the night switch.

(Q) Upon the seventh level of the pilot switch (Fig. 2), I provide a multiple brush comprising four movable contact points or brush fingers resting upon four of the fixed 125 contact points of the level. These brushes in their progress connect together four points at all times, the four points being determined at any time by the position of the brushes since all four rest upon points con- 130

nected to the same wire. At other times, as in No. 3 stop position, two circuits are closed, 127-128 and 127-159. In another instance, 5 No. 11 stop position, three circuits are closed, 127-128, 127-159 and 127-154. By this arrangement of brushes and circuits, I secure in a single level of fixed contact points the advantages of two or even three levels of contact points, in that I close upon the same 10 level frequently two and in one instance three simultaneous circuits.

(R) For a still further economy of the fixed contact points of an automatic switch, that a number of circuits greater than the 15 number of levels of the switch may be obtained, I have provided upon the third level of the pilot switch of Fig. 2, two multiple brushes each of two brush points and each such multiple brush engaging two fixed 20 points of the cylinder. In the operation of these brushes, the wires 114 and 188 are connected by the main brushes until the main brushes leave the point 14X3, being then connected by the auxiliary brushes. Thus while 25 the auxiliary brushes are holding closed the path named, the main brushes are free to close the additional circuit 109-151 upon points 20X3 and 21X3. Thus, two independent 30 circuits are closed by two independent pairs of brushes upon a single level of fixed contact points of the automatic switch. The circuit 109-151 is closed effectively twice in the cycle of operations of the pilot switch through the same fixed points 20X3 and 35 21X3, being closed by the main brushes when between stop position No. 9 and stop position No. 10 and being closed again by the auxiliary brushes immediately after the main brushes leave stop position No. 14. As the 40 switching capacity of such an automatic switch is limited in number of simultaneous circuits by the number of fixed contact points, the utility of increasing the number of simultaneous circuits without increasing 45 the number of fixed contact points is evident.

(SA) At times the switches in an automatic exchange are noted to be off-normal. It is not necessary to go at length into the 50 reasons why or the conditions under which such switches attain an off-normal condition, when not actually in use in promoting or maintaining a telephone conversation. The purpose of the present invention is to accept the off-normal condition of the automatic switches and to restore them to normal condition in readiness for further service, restoration being attained automatically.

In a connective division of the type herein 60 described, when a telephone call is initiated, the pilot switch is set off-normal and immediately the primary connector is set off-normal, the switches then coöperating with each other and with other switches to set up a 65 connection. To maintain the connection,

both the A-switch and the pilot switch must retain off-normal positions. If either the pilot switch or the A-switch return to normal, it is obvious that the other switch should be returned to normal promptly, and 70 the signal controller and interconnector as well, in order that the entire division may attain its normal position of idleness in readiness for further service upon another call. I provide a system of circuits inter- 75 connecting the pilot switch and the A-switch such that the return of either to normal will return the other to normal also.

(SB) In the processes of restoring to normal a connective division, it is required 80 sometimes to care for the condition in which the primary connector is not connected to any line, but has passed to some position in which it is not associated with a telephone line. A circuit (70th) is provided for ad- 85 vancing the A-switch to normal. When the pilot switch reaches that first stop position in which it ordinarily would pass into control of a calling telephone line over circuits through the A-switch, it is controlled automatically to restore its division to normal, the control being effected by a central office 90 circuit local to the division, and passing through normal points of the A-switch. The A-switch thus automatically substitutes a 95 local control circuit for the line circuit when for any cause it is abnormal at a time when it should occupy a line selecting position.

(SC) When the pilot switch reaches normal and at all times when in its normal position, it closes a restoring circuit for the A-switch extending through all off-normal stop positions of the A-switch, but opens in the A-switch when that switch is normal. It closes also a similar circuit for the signal 100 controller, both of these circuits restoring 105 their switches to normal as soon as the pilot switch reaches normal, if for any reason either of the other switches is off-normal at that time.

(SD) In order that different lengths of time limit may be had, yet that the expense of but a single timing device may be incurred, I provide a stepping timer deriving 110 its stepping impulses from a battery and 115 commutators; in connection with the timer, I provide two commutators, a fast one and a slow one, so that the timer may be driven either rapidly or slowly according as it connected with the fast or slow commutator. 120 To associate it with either commutator at the proper time, I carry the timer-drive circuit through the pilot switch and thence to either commutator or to neither, in accordance with the requirements of the connection from time to time as determined by the position of the pilot brushes.

(SE) In providing the division starter with a timer, I carry the drive circuit of the timer through the sub-normal position of the 125 130

division starter, in which position the starter is waiting for the started primary connector to pick up the calling line, and I release and restore the timer between the sub-normal 5 stop positions and the next normal stop position of the starter. The timer points are connected to the starter clutch.

(SF) I provide a novel means for disabling the division starter at such times as 10 all divisions are off-normal, which is to say at such times as no idle division exists so that any action on the part of the starter would be futile.

I accomplish this result by providing a 15 stop position for the starter brushes additional to those stop positions associated with the connective divisions and I provide a circuit passing in multiple to all connective divisions by which any normal connective 20 division will cause the starter to pass its "out of service" position. When all divisions are busy and a call is received, the starter will move until it reaches its "out of service" position where it will stop and 25 await the return of a connective division to normal. As soon as a connective division returns to normal, it will start the division starter, (82nd circuit) from its "out of service" position and the starter will move immediately to the sub-normal starter position 30 corresponding to the now normal connective division, starting the division to serve the waiting call.

(SG) In all large systems of telephone switching certain units of apparatus or certain circuits are duplicated many times and are used for the same purpose, any one being available for service when not engaged by prior use. In manual systems, duplicated 40 trunks are used by manual selection, but the manual operator is prone to select the first of the group if idle. In automatic systems, the automatic selection sometimes compels the use of the first trunk, if idle, the nature 45 of the selecting apparatus being such as to make it impossible to select another device whenever the first device is not in use. It is obvious that if the first unit of duplicated apparatus be in any way defective to prevent 50 the completion of a specific call, that specific call might be repeated innumerable times if not contemporaneous with another call having the same destination, and at every repetition the call would be defeated 55 because of the compulsory repeated selection of the defective unit of apparatus.

I provide a method of using duplicated apparatus or duplicated electrical circuits having a common destination, the units of apparatus being selected in rotation by successive calls, whether contemporaneous or discontinuous, and whether independent calls or repetitions of the same call. Thus, with 60 my improved method of selecting an operating duplicated apparatus, the repetition

of a call will not meet and use the same units of duplicated apparatus, and if the first call shall have failed by reason of any defect in any unit of duplicated apparatus, its repetition will not fail in similar manner by 70 reason of encountering the same defective unit of duplicated apparatus.

I accomplish this desirable result by providing a false busy-test condition.

Upon selecting for use the first unit of 75 apparatus a fact-busy condition is placed upon its guard elements so long as it remains in use. When its use is terminated and the apparatus using it has been disconnected, means provided by my invention continue the busy condition upon its test elements, thus rendering a false busy test or false guard indefinitely upon that unit of apparatus when tested. The first unit of duplicated apparatus being thus busy, either 80 fact or false, the next operation requiring its use will encounter the busy test and will be compelled to select the next unit of the duplicated apparatus. This second unit while used will bear a fact busy and after 85 its use has been discontinued, it will bear a false busy, thus compelling the next test to pass to the third unit of duplicated apparatus. The successive units of duplicated apparatus thus will be guarded with a false busy 90 test until the last of them has been selected for service. In connection with the last, I provide releasing means for the false busy upon all the others. As soon as the last unit 95 of the series of duplicated apparatus has been selected for service, the false busy is removed from all others, but should any remain busy by fact the fact busy is not disturbed. The next search for an idle unit 100 of apparatus will select the first unit and after use will leave upon it a false busy, compelling the selection of a second unit, and so on as before. The last unit of duplicated apparatus therefore becomes a control 105 unit for releasing the false-busy-test condition from all other units.

I provide the release of the false busy from all other units whenever a control unit 110 is tested without regard to whether the control unit is idle or busy, the fact that it is tested being evidence that the rotation of service is complete and that the false busy 115 should be removed to permit the operation of another sequence.

(SH) I find it advantageous to divide a 120 group of duplicated apparatus into two parts, the first part of which is equipped with devices for giving the false busy, the last unit of the first part being the control 125 unit, and the several devices of the second part being at all times free from false busy, so that if idle in fact they may be selected in order of arrangement of their testing terminals. This principle may be applied by using but a single unit as the second part 130

of a group, the single unit or last unit of the whole group then being available for service when the test finds the control unit busy, immediately taking the last unit which presumably will be found idle, and rendering all other idle units free from the false guard for the next succeeding test.

For the application of the methods just described I may provide a relay for each unit of apparatus in the rotational group. The first unit of the group has a locking relay which places a false busy test condition upon the testing terminals of its unit of apparatus and which locks to a circuit passing through normally closed contact points of the relay of the control unit. The second and successive units, if any, each operate likewise to place the false busy upon the testing terminals of their units of apparatus and likewise lock over the same circuit to the points of the relay of the control unit. The relay of the control unit when tested, operates only to break the locking circuit described and to unlock all the relays of all the other units of the rotational group.

I am not limited to the use of relays in this detail, as a cylinder switch may accomplish similar results.

As applied to manual practice, the use of any duplicated unit other than the control, will lock that unit to the control, the units not necessarily being used in strict rotation.

As a modification especially adapted for manual practice, the control relay may be operated from terminals analogous to the test terminals of a unit of apparatus, but having no function other than the control function for the release of the false busy. I term this a "dummy" control trunk.

(SM) In designing a system of registering calls or conversations upon central office meters in automatic exchanges having a pilot switch, I have designed a pilot switch occupying one position while the call bell of the selected or B-line is being rung and occupying another position during conversation. Accessible by the movable brushes of the pilot switch between these two positions, I provide contact points having their circuit path transiently closed by the pilot brushes while the brushes move from ringing position to talking position. The metering path I provide with a source of current and I take it through those points and through the meter of the calling line or A-line, thus completing the metering circuit.

To render an A-line meter operative if the B-line responds and inoperative if the B-line does not respond, I carry the metering circuit through the movable and front contact points of a relay which is charged by the B-line when a station of that line answers the ring. Thus while the pilot brushes may advance from ringing to talk-

ing position without the answering of the B-line, no registration upon the A-line meter will be effected by such movement and only answered calls will be registered, since the relay mentioned will be uncharged at the time of the brush movement upon an unanswered call.

(SN) In connection with metering systems, it is desired sometimes that lines for fire department, police department, the telephone company's offices and even newspapers and doctors or special lines of any description shall be permitted to receive calls originating anywhere in the exchange without causing registration upon the meter of any line calling one of the "free service" lines. It is desired further at times that a line may be changed to such a "free service" without changing the directory number of the line. It is obvious that if a line is to have free service in the sense that no charge is to be made for calls originating upon it, the result may be attained by omitting the meter from the line or ignoring the meter. However, when it is desired that no charge shall be made for calls terminating upon a specified line, even though those calls may originate upon lines equipped with automatic meter devices, I provide such a system of control as will enable the specified line to react upon the metering circuit of the connective division and the metering apparatus of the calling line in such manner as to prohibit its normal operation. In connection with a pilot switch as described, I provide two relays connected with the selected line or B-line, the first of which closes the meter circuit and the second of which causes the pilot brushes to advance; the second relay thus causes the metering circuit to be closed through the first relay while the brushes are moving. In connection with "free service" lines, I provide a reactive circuit which charges the second relay but not the first and thus advances the pilot switch from ringing to talking position while the first relay is still uncharged, so that the metering circuit through the pilot brushes at the time the pilot brushes are passing their meter contact point will be open in the contact points of the first or metering relay and no operation of the meter will ensue. After the talking position has been reached by the pilot switch, the charging of the first relay may be permitted, since it then can not affect the meter.

In manual practice the same effect may be accomplished by providing interfering or interlocking relays, such, that if the first relay be charged before the second, the meter will be operated, while if the second relay be charged before the first, the meter will not be operated. In this case it becomes immaterial with respect to the meter whether the remaining relay becomes charged or not.

(SP) To enable toll operator to speak upon a line already in use for conversation, I provide a means for enabling a trunk from manual toll board to automatic switchboard 5 to gain access to a selected line even though the selected line be in use and guarded by the usual busy-test condition.

The system as a whole is so organized that when a tested selected line is found to be 10 previously engaged, one of the several switches of the connective divisions retains a preliminary position and does not move to its ultimate talking position. By retaining this preliminary position, it accomplishes 15 two purposes; it prevents connection of the calling line with the selected line, and it returns a busy tone to the calling party.

I provide a means in connection with trunks from a manual toll board to an automatic switchboard whereby the said switch 20 may be advanced from its preliminary to its talking position by a manual act of the operator of the manual switchboard when the busy tone is heard upon a trunk.

(SQ) The feature in which the party line telephone differs from the telephone for the exclusive line is found in the presence of an additional step in the signal transmitter, which additional step has its utility in preventing the closing of the telephone speech bridge until after the reverting ring has 30 been made upon the line in case of a reverting call.

(SR) I have not made any effort to prevent a second telephone user upon a party line from listening to a conversation by a first user of his line, my interference device acting only to prevent a second telephone user upon a party line from sending a call 40 or operating his automatic call sender while a first user is upon the line in conversation. My device comprises a blocking magnet for the call sender, which, when the line is in use for conversation, is operated upon the 45 beginning of the movement of the call sender, to prevent the completion of the movement, and therefore to prevent the sending of a call upon a busy line. When the line is not in use for conversation, the blocking magnet is inoperative.

In the complete diagram shown by the combination of Figs. 1, 2, 3, 4, 5 and 6 there is illustrated a connective division which it may be determined is located upon the 55 eighth section of the automatic central office; that is, upon the section serving lines having directory numbers 700-to-799. This is determined by observing that it is necessary to adjust the interconnector of Fig. 5 to have its register on the eighth step off-normal or upon the #7 set of points in the 60 hundreds register to effect the connection to the trunk of four wires leading to the secondary connector of Fig. 6, which secondary connector has in its multiple points the same

lines found in the primary connector of Fig. 1.

In describing the operation of the automatic telephone system herein shown, a typical call will be traced through the operations 70 of setting up the connection, holding the conversation and disrupting the connection. It will be assumed that line #714 being line #14 of Figs. 1, 6 and 7 is calling, and that the selected line is line #705. 75

Wires 421, 422 and 423 may be considered to represent typical wires of any line. That is, wire 421 of line 705 when mentioned is exactly analogous to wire 421 of line 714, and the telephone assumed for line 705 is of 80 the same type as shown in the figures for line 714.

For the purpose of describing the operation of meters and code ringing devices, it may be assumed from time to time that 85 either or both of lines may become lines equipped with any designated type of substation equipment or circuit.

It will be assumed also that, at the beginning of the typical call to be traced, the several switches are idle, and stand in the positions shown in the drawings. 90

The operation of my improved automatic telephone system is as follows:—

(1.) *Primary adjustment.* 95

The relay call finder comprises two hundred and ten relays of which one hundred are line relays, one hundred are cut-off relays and ten (in the top row) are sequence 100 relays. The last are so named since each has the function at times of disabling certain lines from calling while such sequence relay is charged, thus determining a sequence 105 of service among lines calling contemporaneously.

By "calling" in connection with this part of the description, I refer to lines which have initiated a call and have not yet been seized by a primary connector; that is, to 110 lines holding the line relays charged, or attempting to do so. By "simultaneously calling" or "contemporaneously calling" I do not mean simultaneous initiation of a plurality of calls but the simultaneous or contemporaneous existence of a plurality of calls, probably successive in initiation, but overlapping in time between the closing of the first circuit and the 15th circuit for each of them. 115

The auxiliary relays or sequence relays are numbered (Fig. 7) 0-to-9. Line relays are numbered 00-to-99, 14, 21. Cut-off relays are numbered 00'-to-09', 14', 21'.

Multipled through the left contact points 125 of the line relays in horizontal rows are the decimal signal wires for the decimal digits 0-to-9; multiplied through the right contact points of the line relays in vertical rows are the units signal wires for the units digits 130

0-to-9. Minus bus wire or ground terminal of the main battery 200 is connected to the armature points both right and left of the line relays.

- 5 Upon the charging of any line relay by a calling line, its two armatures place earth or minus battery upon two wires, (1st) the decimal wire identifying the decimal digit of the calling line and leading to the decimal controller and (2nd) the units wire identifying the units digit of the calling line and leading to all the primary connectors of the section and leading also to one terminal of the winding of the sequence relay identified with the units of the calling line.

By the charging (1st circuit) of the line relay, a local circuit (2nd circuit) is closed from minus battery through the right armature of the line relay to the lower terminal of the winding of that sequence relay which is located directly above the line relay and through the helix to plus battery. Thus upon the institution of a call by any line, 20 two relays are charged, namely, the line relay and then the corresponding sequence relay.

By the charging of the sequence relay, its right armature points are closed, placing 30 minus battery upon the division starter clutch (3rd circuit) and starting the division starter brushes.

Also by the charging of the sequence relay, the left armature points are opened for 35 the purpose of preventing confusion by two conflicting lines when calling contemporaneously.

The system of circuits and apparatus (paragraph B) for preventing confusion 40 between two conflicting lines calling contemporaneously is as follows:—

With reference to lines having the same units digit: The apparatus of the decimal registers and of the decimal controller will 45 care for contemporaneous calls. The primary connector will adjust itself to the units position, which is the same for both or all of the calling lines, and the decimal controller then will send impulses adjusting 50 the decimal register to some one of the lines, it is immaterial which. If two lines are calling before the decimal controller starts from normal, the decimal wire of the higher number will be engaged first and the decimal 55 register will be adjusted to the line of the higher number. If it should occur that the line of the higher number should call at an instant after the decimal controller brush has passed its decimal wire, then the decimal controller will adjust the decimal register to the line of the lower number. In 60 either case there will be no confusion, one of the lines will be picked up, and the remaining line will be served immediately by 65 another connective division.

With reference to lines having different units digits: confusion sometimes would result in the primary connectors and circuits as organized if several lines having different units were permitted to charge their line 70 relays simultaneously. To avoid this, a series connection is made through the left armature contact points of the sequence relays in such manner that each sequence relay disables all lines to the right in the 75 drawing, namely, all lines having higher units than the number represented by the charged sequence relay.

The precedence thus established among units would tend to discriminate against 80 lines of the highest units. To avoid such discrimination the sequence is changed from time to time by the action of a sequence switch.

For economy in construction, the sequence 85 switch is combined with the division starter (paragraph C), the lower six levels of the cylinder of Fig. 9 being the points of the sequence switch and the upper levels being those points having the functions of starting divisions.

When the starter is in the stop position No. 1, it is in condition to start the first connective division of the section. When it is in its stop position No. 2, it is in condition 95 to start the second connective division of the section and so on through the seven divisions, returning thence to the first division.

By a system of circuits involving the 100 lower six levels of points in the starter cylinder, the sequence among units is changed as follows:—

With the starter brushes in stop position No. 1 or No. 2, ready to start either of the first two connective divisions, a path (1st circuit) is traced from plus battery through starter or sequence switch points in 10th and 9th levels, wire 401 to all line signal relays of "0" units; branching through left contacts of sequence relay 0 to all line signal relays of "1" units; branching through left contact points of sequence relay 1 to all line signal relays of "2" units; branching 110 through left contact points of sequence relay 2, wire 404, through starter points in 12th and 11th levels, through wire 403, to all line signal relays having "3" units; branching through left contact points of sequence relay 3 to all line signal relays having "4" units; branching through left contact points of sequence relay 4 to all line signal relays having "5" units; branching 115 through left contact points of sequence relay 5, through wire 406, starter points in 14th and 13th levels, wire 405, to all line signal relays having "6" units; branching through left contact points of sequence relay 6 to all line signal relays having "7" units; branching 120 through left contact points of sequence relay 7, through wire 407, to all line signal relays having "8" units; branching through left contact points of sequence relay 8, through wire 408, to all line signal relays having "9" units; branching 125 through left contact points of sequence relay 9, through wire 409, to all line signal relays having "0" units; branching through left contact points of sequence relay 10, through wire 410, to all line signal relays having "1" units; branching through left contact points of sequence relay 11, through wire 411, to all line signal relays having "2" units; branching through left contact points of sequence relay 12, through wire 412, to all line signal relays having "3" units; branching through left contact points of sequence relay 13, through wire 413, to all line signal relays having "4" units; branching through left contact points of sequence relay 14, through wire 414, to all line signal relays having "5" units; branching through left contact points of sequence relay 15, through wire 415, to all line signal relays having "6" units; branching through left contact points of sequence relay 16, through wire 416, to all line signal relays having "7" units; branching through left contact points of sequence 130

relay 7 to all line signal relays having "8" units; branching through left contact points of sequence relay 8, to all line signal relays having "9" units; branching through left contact points of sequence relay 9 to wire 402, to open points in the starter cylinder, in 10th level.

With the starter brushes in position No. 1 or No. 2 the lines stand in a sequence in which "0" units come first, progressing through in order, and "9" units come last. In the case of lines of different units calling contemporaneously, the line having the lower units digit will charge its line relay, which will charge its corresponding sequence relay, which in turn by its left contact points will open the circuit of the line relay of the line having the higher units, so that the line having the higher units cannot charge any relay until after the line having the lower units has been taken by a primary connector. The order of precedence is 1, 2, 3, 4, 5, 6, 7, 8, 9.

When the brushes of the starter have progressed as far as their stop positions No. 3. or No. 4, the sequence among the lines is changed.

Circuit (1st circuit) now extends from plus battery over starter points in 12th level, through brushes to points in 11th level, wire 403, to all line signal relays having "3" units; branching through left contact points of sequence relay 3 to all line signal relays having "4" units; branching through left contact points of sequence relay 4 to all line signal relays having "5" units; branching through left contact points of sequence relay 5, wire 406, starter points in 14th and 13th levels, wire 405, to all line signal relays having "6" units, the "8" units, then "9" units and as before over wire 402, to starter points in 10th level and continuing starter brushes to starter points in 9th level, wire 401, to line signal relays having "0" units, then "2" units and to wire 404, which extends to open points in the starter.

Thus the sequence of lines when the 3rd or 4th connective division is to be started will give precedence to units "3" and higher over units "0" units "1" and units "2" the order being 3, 4, 5, 6, 7, 8, 9, 0, 1, 2.

When starting the 5th, 6th, and 7th connective divisions, the lines will have an order of precedence among units as follows: 7, 8, 9, 0, 1, 2, 3, 4, 5.

Thus with the permuting arrangement of circuits through the sequence switch or starter, the lines having higher digits will not be discriminated against, since when two lines having high and low digits call contemporaneously, the machine switchboard sometimes will serve the higher number first and sometimes will serve the lower number first. With lines 11 and 99 calling at the same time, the 1st or 2nd connective

division would serve line 11 before line 99, while any one of the remaining five divisions would serve line 99 before line 11. With lines 33 and 99 calling simultaneously, the first four divisions would serve 33 before 99, while the last three divisions would serve 99 before 33.

When a call is started at the telephone of Fig. 10, the arm 242 steps mechanically to the pin 244 and earth is placed upon line conductor 421. This will charge the line relay (1st circuit), charge the sequence relay (2nd circuit), move the division starter (3rd circuit) from normal to off-normal, move the pilot of an idle connective division (4th circuit) from No. 1 to No. 2 stop position, and start simultaneously by the primary connector (5th circuit) of the division and the decimal controller (7th circuit) of the section.

The 1st circuit (charging line relay) extends from the substation ground or minus battery (Fig. 10) pin 244, arm 242, wire 421 (Fig. 7) closed points of cut-off relay 14' and helix of line relay 14 and to vertical bus wire common to ten line relays in a vertical row to (not through) closed left contact point of sequence relay 4 and branching to and through closed left contact point of sequence relay 3, wire 403, starter points 95 in 11th and 12th levels, wire 404, closed left contact points of sequence relays 2, 1, 0, wire 401, starter points in 9th and 10th levels, the starter brushes being on the first set of points as shown in the drawing, the first circuit then terminating upon wire 424 which is connected to plus battery.

The second circuit (charging sequence relay) extends from minus battery (Fig. 7) wire 409, right closed contacts of charged line signal relay 14, vertical bus wire leading to helix of sequence relay 4, through helix and to plus battery.

The 3rd circuit (charging starter clutch) extends from minus battery (Fig. 8) over wire 420, wire 419, movable and back contact points of discharged relay 250, wire 407, (Fig. 7) right contact points now closed of charged sequence relay 4, wire 408 (Fig. 9) division starter cylinder points 115 1X3-4, wire 501, division starter clutch magnet, wire 503, and to plus battery. The 4th circuit (charging pilot clutch) extends from minus battery (Fig. 9) over wire 418, division starter points 3X5-6, wire 121 (Fig. 2) 120 pilot points 1X14-2X14, wire 192 pilot clutch magnet 215 and to plus battery.

The 5th circuit (charging primary connector clutch) extends from minus battery (Fig. 3) over left movable and back points 125 of uncharged relay 201, wire 102 (Fig. 2), pilot points 3X10-11 wire 186 (Fig. 1) primary connector clutch magnet 216 and to plus battery.

The 7th circuit (charging decimal con-

430

troller clutch through pilot points) extends from minus battery (Fig. 3) over points of uncharged relay 201, wire 102 (Fig. 2), pilot points 3X13-12, wire 123 (Fig. 8) decimal controller clutch magnet 217 to plus battery.

The primary connector and decimal controller being in motion, the primary connector moves (5th circuit) until it completes its searching circuit (6th circuit) through the charged line relay. This charges relay 201 and breaks 5th and 7th circuits. The decimal controller moves and closes its searching circuit through the charged line relay (8th circuit) charging the decimal relay 250 which locks (9th circuit) and the decimal controller then sends impulses (10th circuit) to the register of the primary connector.

The 6th circuit (charging relay 201 to break 5th and 7th circuits) extends from minus battery (Fig. 7) over wire 409, right points of charged line relay 14, wire 454 (Fig. 1) to cylinder point 17X1 of the primary connectors; when moving brush 233 reaches point 17X1, 6th circuit is completed through brush 233, brush 234, point 39X1, wire 115, (Fig. 2) pilot points 3X2-4X2, wire 101 (Fig. 3) helix of relay 201, plus battery.

The 8th circuit (charging decimal relay) extends from plus battery (Fig. 8) over wire 410, left helix of decimal relay 250, wire 413, segment 232, moving brushes, decimal wire 431, (Fig. 7) left points of charged line relay 14, wire 409, and minus battery.

The 9th circuit (locking relay 250) extends from minus battery (Fig. 8) over wire 420, wire 419, movable and front points of charged relay 250, wire 505, left helix of relay 250, wire 410 and plus battery.

The 10th circuit (charging decimal register by decimal impulses) extends from minus battery (Fig. 8) over wire 420, wire 419, movable and front points of charged relay 250, wire 505, wire 413, segment 232 and brushes of decimal controller, and thence as a separate impulse over each of the small segments connected to the wire 129 and located at the right of the small segment identifying the decimal digit of the calling line, over wire 129 (Fig. 2), pilot points 4X1-3X1, wire 119 (Fig. 1) cylinder points and moving brush in third quadrant register magnet 214, moving brush 266, cylinder points and plus battery. By these impulses over 10th circuit, the decimal register of the primary connector or A-switch is adjusted to its proper position for the selection of the calling line. In the instance assumed, two impulses are received by the magnet 214.

The brushes of the decimal controller stop 65 in off-normal position upon segments 230

and 232, the circuit having been broken while the brushes were in motion. The pilot brushes move (11th circuit) from No. 2 to No. 3 stop position, interrupting 5th, 6th, 7th, 10th, and 11th circuits. The starter 70 brushes move (12th circuit) to their next normal position (points No. 5). The decimal controller moves (13th circuit) to normal and discharges (14th circuit) relay 250. Meanwhile the pilot has placed the guard 75 condition (15th circuit) upon the calling line or A-line.

The 11th circuit (charging pilot clutch through No. 2 position) extends from minus battery (Fig. 8) over wire 420, wire 419, 80 closed contact points of charged relay 250, wire 505, wire 413, segment 232, brushes and segment 230 of decimal controller, wire 122 (Fig. 2) pilot points 3X14-4X14, wire 192, pilot clutch magnet 215 and to plus battery. 85

The 12th circuit (charging clutch of off-normal division starter through off-normal pilot points) extends minus battery (Fig. 8) over wire 420, wire 127 (Fig. 2) pilot points 39X7-7X7, wire 128 (Fig. 9) division 90 starter points 3X3-4, wire 501, division starter clutch magnet 218, wire 503 and to plus battery.

The 14th circuit (discharging decimal relay 250) extends from minus battery (Fig. 95 8) over wire 420, wire 419, closed points of charged relay 250, wire 505, wire 413, segment 232, normal brushes, segment 231, wire 414, right helix of relay 250, wire 410 and to plus battery.

The magnetic effect produced upon the core of relay 250 by current over 14th circuit is equivalent in strength and opposed in direction to the magnetic effect produced upon that core by current over 9th circuit. 100 The core therefore is neutralized magnetically and the armature is released, interrupting both 9th and 14th circuits and closing at relay 250 the path of 3rd circuit, subject to closure at the sequence relays for the 105 actuation of the division starter on a subsequent call.

The 15th circuit (A-line guard circuit) extends from minus battery (Fig. 7) over wire 409 to lower helix terminals of all line 111 cut-off relays, through the helix of line cut-off relay 14 over the guard wire 423 individual to the line identified, to the guard point of the line (Fig. 1) in the A-switch, cylinder point 6X9, cylinder brush, decimal 120 register point, third decimal register brush (which has been adjusted to that point) cylinder brush on 6th level in second quadrant, collector segment on the 6th level in second quadrant, wire 114, pilot points 6X3-125 7X3, wire 188 (Fig. 3) resistance 211 and to plus battery.

The next step in setting up a telephone connection is the transmission of signals from the calling telephone indicating a por- 120

tion of the directory number of the line with which connection is desired, and in response the connective division selects a secondary connector or B-switch having the terminals 5 of the line to be called; the next step is the transmission of signals from the calling telephone indicating the remainder of the directory number, and in response the division causes the selected B-switch to connect with 10 the line desired.

The action to be covered by this part of the description is the reading or interpretation of the dial setting of the call sender and the adjustment of sundry automatic switches 15 in accordance therewith.

In its No. 3 stop position, the pilot switch provides a path (16th circuit) to start the signal controller, a path (18th circuit) for impulses from the signal controller to propel 20 the call sender, arm 242, a path (19th circuit) for signals from the call sender, arm 242, to the signal relay 201 (locking by 20th and 22nd circuits), a path (17th circuit) from the signal controller to the thousands 25 register, a path (21st circuit) from the signal controller to the hundreds register, and paths (23rd and 24th circuits) for the control of the hundreds interconnector to effect its search for an idle trunk.

30 The 16th circuit (charging clutch of signal controller through pilot points in No. 3 stop position) extends from minus battery (Fig. 2) over wire 109, pilot points 7X13-12, wire 130, (Fig. 4) signal controller points 35 1X11-12, wire 511, wire 506, a controller clutch magnet 213, and to plus battery.

The signal controller moves its brushes, breaks 16th circuit and stops its brushes upon its 43rd set of points. While moving, 40 the brushes close 17th, 19th, 20th, 21st, and 22nd circuits.

The 17-1st circuit (first impulse for thousands register) extends from minus battery (Fig. 4) over wire 425, signal controller 45 points 5X5-6, wire 131, (Fig. 2) pilot points 7X4-6X4, wire 195, thousands register magnet and plus battery.

The 17th circuit (charging thousands register magnet) extends from minus battery 50 (Fig. 3) over left movable and back points of relay 201, wire 432, (Fig. 4) signal controller points 5X5-6, wire 131, (Fig. 2) pilot points 7X4-6X4, wire 195, ringing register magnet 236, and to plus battery.

55 Each impulse over 17th circuit moves toward the right, the four brushes, 311, 312, 313, 314 of the ringing register. Impulses are sent from the successive signal controller points 5X6, 7X6 and so on, so long as relay 60 201 remains uncharged. Relay 201 is charged by 19th circuit.

The 18th circuit (charging telephone call sender magnet) extends from plus battery (Fig. 4) over signal controller points 2X1-2, 65 wire 132 (Fig. 2) pilot points 7X1-6X1,

wire 112 (Fig. 1) through A-switch as adjusted line conductor 422 (Fig. 10) wire 426, through switch 247 (now closed) telephone magnet 248 and to earth or minus battery.

This circuit is contained on controller 70 points 3X1-2 and 4X1-2, and is repeated in impulses on the successive controller points 6X2 and so on, and charges the telephone magnet twenty times while the signal controller brushes are moving from the first set 75 to the 43rd set of points, that is, from normal position to their off-normal stop position.

The 19th circuit (signaling from telephone call sender) extends from substation 80 earth or minus battery, through the telephone's call sender, only when 18th circuit is closed, and after a sufficient number of impulses have been sent to the register, as required by the sender dial setting. When 85 18th circuit is closed, magnet 248 is charged, and arm 242 may rest upon one of the points 241 connected to indicator points under indicator brushes 240. With magnet 248 uncharged, arm 242 rests upon blank intermediate points, or upon points not connected 90 to indicator points.

With 18th circuit closed and arm 242 resting upon a point 241 connected to an indicator point under an indicator brush 240, 95 19th circuit extends from substation earth connection, brush 240, pin 241, arm 242, wire 427, line wire 421, (Fig. 1) through the A-switch as adjusted, to wire 113, (Fig. 2) pilot points 6X2-7X2 wire 101, (Fig. 3) 100 helix of relay 201 and to plus battery.

The 20th circuit (locking relay 201) extends from minus battery (Fig. 4) over wire 425, signal controller 9th and 10th levels in first half of cylinder, wire 439 (Fig. 3) 105 right contact points of charged relay 201, wire 508, helix of relay 201, and to plus battery. The 20th circuit is broken as the signal controller brushes leave their 21st set of points.

The 21st circuit (charging hundreds register for second directory digit) extends from minus battery (Fig. 3) over left movable and back contact points of discharged relay 201, wire 432, (Fig. 4) controller 115 points 23X5-6, wire 138, pilot points 7X11-10, wire 147, (Fig. 5) interconnector point 23X1, cylinder brush, hundreds register magnet 235, interconnector normal switch, and to plus battery.

The 21st circuit is repeated in impulses for ten impulses, or until the charging of the signal relay 201 by a repetition of 18th circuit.

The 22nd circuit (locking relay 201) extends from minus battery (Fig. 4) over wire 425, signal controller points on 9th and 10th levels in second half of cylinder, wire 439, (Fig. 3) right contact points of charged relay 201, wire 508, helix of relay 201, and to 125 130

plus battery. The 22nd circuit is broken as the signal controller brushes leave their 1st set of points.

At this stage of the process of setting up the connection, it becomes necessary for the interconnector to select and seize an idle secondary connector. For this search and seizure I provide novel busy-test circuits (paragraph D) extending the influence of the act of testing to test for the normal or off-normal position of the secondary connector rather than for the engaged or disengaged condition of the conductors leading to the switch. At the same time, I effect the desired result with but the usual four conductors leading to the secondary connector, with but the usual three points per line in the secondary connector, and with the use of but one battery.

In applying my invention I take three taps from the battery 200, two terminal taps, plus and minus, and an intermediate tap over the conductor 400. (Fig. 11). I provide an off-normal switch 237, which isolates the test conductor 444 from the battery when the B-switch is normal and when off-normal connects the test conductor 444 to plus battery through an operating magnet 238. By applying minus battery at the interconnector terminals of the test conductor 444 (to 141, and for example through pilot points 29X12-13 when brushes are in No. 13 stop position, to wire 109 and to minus battery for release of the B-switch) the magnet 238 may be operated as desired. In this way the test conductor 444 bears sometimes the plus potential through the magnet 238 and sometimes the minus potential from pilot point 29X12 or 10X10, the B-switch being busy in either case. To test in such manner that the busy condition may be shown in either case, I connect my test relay 203 from the test wire 444 to the median-potential wire 400 (23rd circuit) so that the test relay becomes charged from either the plus or minus potential of the test wire 444 and may remain uncharged from 444 only when 444 is isolated from the main battery by the open position of the off-normal switch 237 as caused and held by the normal B-switch in its normal position of readiness for service.

Associated with 23rd or testing circuit, 24th circuit operates to initiate the searching movement of the interconnector and to continue that movement whenever a B-switch is engaged which tests busy by the test of the 23rd circuit.

The 23rd circuit (interconnector's search) extends from 20-volt tap of 30-volt plus battery, or two-thirds pressure over wire 400 (Fig. 2) pilot points 40X9-39X9 wire 175 (Fig. 3) helix of relay 203, wires 521 and 107 (Fig. 2) pilot points 6X11-10, wire 141,

(Fig. 5) interconnector point 12X2, bridged 65 brushes to interconnector point 23X2, and to minus battery. This circuit charges relay 203 as soon as the pilot switch reaches its No. 3 stop position.

The 24th circuit (charging interconnector clutch) extends from minus battery (Fig. 4) over wire 425; controller points 43X9-10, wire 434, (Fig. 3) right movable and front contact points of charged relay 203 wire 104, (Fig. 2) pilot points 6X5-7X5, wire 143 75 (Fig. 5) interconnector clutch magnet 219, and to plus battery.

The interconnector clutch thus is charged when the controller brushes reach 43rd set of points or off-normal stop position and 80 the interconnector cylinder brushes are moved toward the right. The 24th circuit, which causes the brushes to move, passes through the contact points of relay 203, and in moving the brushes, breaks the helix of 85 relay 203, (23rd circuit) and discharges relay 203. At this time, while relay 203 is discharged, the interconnector clutch dog is riding upon the edge of the clutch disk and the points of the first trunk to a secondary 90 connector or B-switch are engaged before the dog drops into the notch corresponding to that trunk.

Assuming that the secondary connector or B-switch is busy, the 2nd variation of the 95 23rd circuit, or 23-2nd circuit, is formed (paragraph C).

The 23rd-2nd circuit (off-normal B-switch) extends from 23rd circuit from wire 141 through the hundreds register as adjusted, through the moving cylinder brush of the interconnector switch to the wire 444 of the B-switch being tested, through the closed off-normal points 237 of the B-switch, wire 514, clutch magnet 238, and to 30-volt 105 plus battery. This circuit, by reason of its low potential (10 volts or one-third full plus) and its high resistance, does not carry sufficient current to charge the B-clutch magnet to attract its armature, (it carries 110 a current equivalent to about one-sixth the current normally taken by the B-clutch for operation of the clutch) but it charges the relay 203, which in turn charges the interconnector clutch magnet 219, continuing the 115 movement of the interconnector brushes to engage the points of the next trunk.

Assuming that the secondary clutch magnet or B-clutch magnet is charged (in which case minus battery is found upon wire 444 120 over 34th or 61st circuit, which see) at the time the 23rd circuit is closed to wire 444, then relay 203 will be charged over the 3rd variation of the 23rd circuit or 23-3rd circuit.

The 23-3rd circuit (charged B-clutch) extends from minus battery encountered upon wire 444, through the moving interconnector

- brushes, wire 141, and so on, to the 20-volt (or two-thirds plus) potential on pilot point 6X13, from wire 400. This charges relay 203 before the interconnector clutch 5 dog drops into the notch corresponding to the B-switch being tested, and the interconnector brushes thus are carried to the next set of contact points, leading to the next B-switch.
- 10 The 23-1st circuit (normal B-switch) extends from 23rd circuit from wire 141, through the moving interconnector switch to the wire 444 which is found open at the B-off-normal contact points 237 between wires 444 and 514. This pair of contact points will be found open when the B-switch is normal and will be found closed at all other times, being closed when either cylinder brushes or register brushes of the B-switch are off-normal, or both.
- 15 Relay 203 is not charged by the 1st variations of the 23rd circuit and the dog of the interconnector clutch drops into the notch corresponding to the B-switch tested.
- 20 An idle B-switch having been found thus, the first action is to set it off-normal to close its test springs 237, thereby rendering it busy by test to other selectors. This is done by 25th circuit at the same time 26th circuit operates to start the pilot switch from its No. 3 stop position.
- 25 The 25th circuit (preliminary impulse for charging B-register) extends from minus battery (Fig. 4) over wire 425, controller points 43X9-10, wire 434 (Fig. 3) right movable and back contacts of discharged relay 203, wire 435 (Fig. 5) closed contact points 251 of discharged interconnector clutch, wire 146 (Fig. 2) pilot points 7X6-6X6, wire 142, (Fig. 5) through interconnector as adjusted, wire 448, (Fig. 6) switch-cylinder point 12X6, cylinder brush, register brush third from top, register point 1X3, wires 428 and 429, register magnet 252, wire 430, cylinder brush, cylinder point 23X1, and to plus battery.
- 30 The 25th circuit had not been closed before this idle B-switch was engaged because, when relay 203 was discharged, points 251 were open, and the reverse.
- 35 The 26th circuit (charging pilot clutch through No. 3 stop position) extends from minus battery (Fig. 4) over wire 425 controller points 43X9-10, wire 434 (Fig. 3), right movable and back contact points of discharged relay 203, wire 435 (Fig. 5) interconnector clutch contact points 251 now closed, wire 146 (Fig. 2), pilot points 6X14-7X14, wire 192, pilot clutch magnet 215, and to plus battery.
- 40 In case the interconnector does not find an idle B-switch in its search, the pilot switch will be started from its No. 3 stop position over the 1st variation of the 26th
- 45 circuit. This circuit is closed by the movable member 254 passing between the two fixed members 253 and 253'. The 26-1st circuit (charging pilot clutch through No. 3 stop position after unsuccessful interconnector search) extends from minus battery (Fig. 5) through contact points 253', 254, 253 which are closed by member 254 after the interconnector brushes have passed the last trunk position in the cylinder, then over wires 146', 146, (Fig. 2) pilot points 6X14-7X14, wire 192, pilot clutch magnet 215 and to plus battery.
- 50 The pilot brushes take their No. 4 stop position, occupying the points of the 8th and 9th sets. The signal controller now advances to its normal, in turn advancing the pilot switch to No. 5 pilot stop position, and then the signal controller begins its second revolution, in the course of which it adjusts the B-register and the B-cylinder in accordance with the setting of the call sender of the telephone line being served.
- 55 The 27th circuit (charging signal controller clutch through No. 4 pilot stop position) extends from minus battery (Fig. 2) over wire 109, pilot points 8X13-12, wire 133 (Fig. 4) controller points 43X11-12, wire 506, controller clutch magnet 213, and to plus battery.
- 60 The controller advances to its normal, with brushes on 1st set of points, as drawn in the fig. 4c, using 28th circuit.
- 65 The 28th circuit (charging pilot clutch through No. 4 pilot stop position) extends from minus battery (Fig. 4) over wire 425, controller points 1X9-10, wire 134, (Fig. 2) pilot points 8X14-9X14, wire 192, pilot clutch magnet 215, and to plus battery. The pilot switch takes its No. 5 stop position with its brushes on the 10th and 11th sets of cylinder points, and closes the 29th circuit.
- 70 The 29th circuit (charging signal controller clutch through No. 5 pilot stop position) extends from minus battery (Fig. 2) over wire 109, pilot points 11X13-12, wire 130 (Fig. 4) controller points 1X11-12, wires 511 and 506, controller clutch magnet 213 and to plus battery.
- 75 The controller brushes move until they reach their 43rd set of points. In passing to normal, they have sent to the telephone call sender magnet 248, one impulse over 30th circuit, and in their second revolution they send a second set of impulses twenty in number, over 31st circuit.
- 80 The 30th circuit (supplementary to 31st circuit) extends from plus battery (Fig. 4) over signal controller points 44X1-2, wire 135 (Fig. 2) pilot points 8X5-9X5 (the pilot at this time being in No. 4 stop position), wire 112 (Fig. 1) through A-switch as adjusted, line 422 to the telephone (Fig. 10) through wire 426, points 247, telephone mag-

net 248 and to earth or minus battery. This circuit is closed but once, furnishing but a single impulse. It is followed immediately by 31st circuit, similar to 18th circuit except in the pilot switch points.

The 31st circuit (charging telephone call sender magnet) extends from plus battery (Fig. 4) over signal controller points 2X1-2, wire 182 (Fig. 2) pilot points 11X1-10X1, 10 wire 112, (Fig. 1), through A-switch as adjusted, line conductor 422 to the telephone, (Fig. 10) and through telephone magnet 248 to earth or minus battery.

This circuit is repeated in impulses on the successive controller points giving twenty impulses and forming a total of twenty-one impulses for 30th and 31st circuits taken together.

The 32nd circuit (first impulse for B-register for third directory digit) extends from minus battery (Fig. 4) over wire 425, signal controller points 3X5-6, wire 181, (Fig. 2) pilot points 10X4-11X4, wire 144, (Fig. 5) through interconnector switch as adjusted, 25 wire 442 (Fig. 6) cylinder point 1X1, cylinder brush, wires 431 and 429, register magnet 252, wire 430, cylinder brush, cylinder point 23X1 and to plus battery. The impulses are sent over 32nd circuit until it is interrupted by relay 201, caused by current flowing over 33rd circuit.

The 33rd circuit (signaling from telephone call sender) extends from substation earth or minus battery (Fig. 10) through the telephone's call sender, only when 31st circuit is closed over elements 240, 241, 242, 247, then over line wire 421, in Fig. 1, through the A-switch as adjusted, wire 113, (Fig. 2), pilot points 10X2-11X2, wire 101, (Fig. 3) helix of relay 201 and to plus battery.

Relay 201 locks over 20th circuit, repeated, (which see) and is discharged when the 20th circuit is broken as the signal controller brushes leave their 21st set of points.

The 34th circuit (charging B-clutch for 4th directory digit) extends from minus battery (Fig. 3) over left contact points of discharged relay 201, wire 432 (Fig. 4) wire 513, 4th and 3rd levels in second half of signal controller, wire 136, (Fig. 2) pilot points 10X11-10, wire 141, (Fig. 5) through interconnector as adjusted, wire 444, (Fig. 6) through closed off-normal points 237 of B-switch, wire 514, clutch magnet 238 and to plus battery.

This circuit is closed continuously rather than by impulses and determines the B-switch cylinder adjustment by the duration of its closure, being equivalent to a set of impulses with the interstices closed. To render the angle of adjustment proper, the B-switch brushes are geared to one-half the speed of the controller brushes and pass but 65 one set of points for each two sets passed

by the controller brushes. The circuit is interrupted by relay 201, under the operation of 38rd circuit repeated, the relay 201 then locking over 22nd circuit repeated.

The directory switches, those taking adjustment by the directory number of the called line or B-line as indicated by the setting of the A-line call sender, and comprising the thousands or ringing register, the hundreds or interconnector register, the secondary or B-register and the secondary or B-cylinder, now have been adjusted. The B-switch now connects the three conductors of the B-line to conductors leading to the pilot switch.

80

(3.) Test and first ring.

The next set of operations comprises the testing of the selected line to determine its busy or idle condition, the returning of the busy-tone signal to the calling line if the selected line or B-line be found busy, and the giving of a first signal ring upon the selected line if it be found idle.

The pilot switch is started (35th circuit) and the busy test of the selected line (paragraph F) is made while the pilot is in motion between No. 5 and No. 6 stop positions. The result of the busy test is recorded by the relay 204. When the pilot brushes reach No. 6 stop position relay 204 will be found charged (36-1st circuit) and locked (37th circuit) if the line has tested "busy" (then see 47th circuit and following) or will be found uncharged (36th circuit) if the line has tested "not busy". Then the signal controller (38th circuit) is moved to normal, the guard condition (39th circuit) is placed upon the selected line, and the pilot moves (40th circuit) to its next stop position.

The 35th circuit (charging pilot clutch through No. 5 pilot stop position) extends from minus battery (Fig. 4) over controller points 43X9-10, wire 137 (Fig. 2) pilot points 10X14-11X14, pilot clutch magnet 215, and to plus battery.

The 36th circuit (busy test upon idle line) extends from minus battery (Fig. 3) left to right, through helix of relay 204, wires 115 518 and 106, (Fig. 2) pilot points 12X3-13X6, wire 142, (Fig. 5) interconnector as adjusted, to wire 448 through the B-switch as adjusted to wire 423, or guard wire of the selected line. From the guard wire, if the selected line be free, 36th circuit extends to the cut-off relay helix and to minus battery (the point beginning) furnishing no current to charge the relay 204.

The 36-1st circuit (busy test upon an engaged line) extends farther from the guard wire 423 through the circuits of the guard-connective division, through points in its pilot switch, 3rd or 6th level, from No. 8 to No. 12 stop positions, except the test

125

130

position while in motion between stop 5 and stop 6, through resistance (as 211 or 212 of Fig. 3) and to plus battery. This variation of the 26th circuit charges relay 204, which 5 locks over 37th circuit, and remains so locked when the pilot switch reaches its No. 6 stop position and until the pilot switch leaves its No. 6 stop position. In a reverting call the pilot brushes are upon points, 12-10 13X3 when the test is made and the calling line is found unguarded and relay 204 is not charged.

The 37th circuit (locking relay 204) extends from minus battery (Fig. 3) through 15 the helix of relay 204, wire 522, closed left contact points of charged relay 204, wire 190, (Fig. 2) pilot points 12X10X11 wire 182, (Fig. 3) through resistance 212 and to plus battery.

20 The 38th circuit (charging signal controller clutch after test upon an idle line) extends from minus battery, (Fig. 3) over right movable and back contact points of uncharged relay 204, wire 105, pilot points 25 14X13-12, wire 133, (Fig. 4) signal controller points 43X11-12, wire 506, signal controller clutch magnet 213 and to plus battery. The signal controller moves to normal position completing 39th, 40th, 41st, 43rd, 30 52nd and 16th circuits.

The 39th circuit (guard for B-line) extends from plus battery (Fig. 3) through resistance 212, and over wire 412, (Fig. 4) controller points 1X1-2, wire 156 (Fig. 2)

35 pilot points 15X6-16X6, wire 142, (Fig. 5) through interconnector as adjusted, wire 443, (Fig. 6), B-switch as adjusted, wire 423 of selected line (Fig. 2) through cut-off relay helix to wire 409 and to minus battery. Current over 39th circuit charges the 40 cut-off relay and establishes a guard condition upon the B-line, as soon as the pilot brushes reach their No. 7 stop position. The potential upon the guard wire 423 of the 45 B-line is about one-half that of the main battery 200 the resistance of the cut-off relay helix being about the same as that of the resistance element 212.

The 40th circuit (charging pilot clutch 50 through No. 6 stop position and through signal controller after test upon an idle line) extends from minus battery (Fig. 4) over signal controller points 1X9-10, wire 134, (Fig. 2) pilot points 13X14-14X14, wire 55 192, pilot clutch magnet 215, and to plus battery.

The pilot brushes move to their No. 7 stop position, engaging 15th and 16th sets of pilot points, in which position they await 60 the beginning of the next code ringing cycle as determined by the engagement of the commutator 276 with its brush, closing 41st circuit.

The selected line now is to be given a 65 first ring by giving one code ring upon the

B-line prior to the restoration of the call sender of the calling line to its normal position to permit the A-line hook to be raised. This is effected in the following order:

Pilot brushes in stop position No. 7 await 70 the beginning of a code ringing cycle. Pilot brushes in stop position No. 8 close circuits to the A-line and B-line independently and currents pass first to the B-line to ring its signal bell or bells according to code and 75 then to the A-line to set its call sender forward to normal position. Pilot brushes then pass to No. 9 stop position and there await the lifting of the hook lever of either calling or called station.

The 41st circuit (charging pilot clutch through No. 7 stop position before the first ring) extends from minus battery (Fig. 3) through commutator 276, wire 446, (Fig. 4) controller points 1X4-3, wire 181, (Fig. 2) 80 thousands register or ringing register, lowest level of points, lowest brush 314 of that register, wire 198, pilot points 15X14-16X14, wire 192, pilot clutch magnet 215, and to plus battery. The pilot brushes are advanced from No. 7 stop position into No. 8 stop position at an instant between code rings. In their No. 8 stop position they engage the 17th and 18th sets of pilot points.

The 42nd circuit (charging ringing relay 95 205 through No. 8 pilot stop position for first ring) extends from minus battery (Fig. 3) through commutator 271, (Fig. 2) ringing register point 2nd from left 3rd from top, ringing register brush 313, adjusted upon that point, wire 173 (Fig. 3) right to left through helix of relay 205, wire 108, (Fig. 2) pilot points 17X12-13 and to plus battery.

There are four variations from this circuit, the selection of one of the five circuits being determined by the position of the ringing register brushes, and current is taken through commutator 271, 272, 274 or 275 according to the setting of the ringing 100 register brushes. Each of the five variant circuits for the helix of relay 205 is closed in two positions of the ringing register brushes, and the two positions are distinguished from each other by the reversal of 115 the wires 196-197 upon the upper two levels of ringing register points. The three brushes 311, 312, 313, thus take ten combinations of ringing circuits by selecting at the same time among the five variations of 120 42nd circuit and between the two variations of 43rd circuit.

The 43rd circuit (ringing B-station first ring) extends from the earth connection of the ringing generator 210, (Fig. 3) over 125 wire 197, (Fig. 2) ringing register point, ringing register brush, wire 172, (Fig. 3) right front and movable contact points of charged ringing relay 205, wire 438, (Fig. 4) signal controller points 1X8-7, wire 155, 130

(Fig. 2), pilot points 17X5-18X5, wire 148, (Fig. 5) through interconnector switch as adjusted, wire 441, (Fig. 6) through B-switch as adjusted, line conductor 421 of the B-line (Fig. 10) through the ringing bridge comprising ringer and condenser 245 and (if not a party line) returning over line conductor 422 (Fig. 6) through the B-switch as adjusted, wire 442, (Fig. 5) 10 interconnector switch as adjusted, wire 144, Fig. 2, pilot points 17X4-18X4, wire 153, (Fig. 4) signal controller points 1X5-6, wire 437, (Fig. 3) left movable and front contact points of charged ringing relay 205, 15 wire 171, top ringing register brush, ringing register point, wire 196, (Fig. 3) and to the generator of alternating ringing currents 210.

The 43rd circuit has one variation as described above. For 43rd circuit, the ringing ground is applied to wire 421 of the line and the ringing current is passed over wire 422 to the party line bells. In the variation of the 43rd circuit, the ringing ground 25 is applied to wire 422 and the ringing current is passed over wire 421 to the party line bells. If the selected line be a party line with grounded bells, then the bells will be rung selective in two groups by the selection of the 43rd circuit or its variation but if the selected line be a line with but one telephone and a bridged bell circuit from wire to wire, then the bell will be rung by either the 43rd circuit or its variation.

The call sender arm 242 of Fig. 10 was advanced one full step, from 243 to 244, mechanically by the act of the telephone user in initiating the call. It has been advanced forty-one full steps, from 243 to 253, 30 electromagnetically by forty-one impulses from the signal controller over 18th, 30th, 31st circuits. It now rests on point 253 and requires one final step to advance it to normal pin 243 to complete the talking bridge from 421 through 427, 242, 243 receiver, transmitter and 246 to 422.

The bell of the B-line being rung once as described, the call sender of the A-line is stepped to its normal or talking position by current over 44th circuit.

The 44th circuit (charging magnet of the calling telephone call sender over wire 422 after first ring) extends from earth or minus battery at the telephone (Fig. 10) through the call sender magnet 248, over wire 422, of the A-line (Fig. 1) through the A-switch as adjusted, wire 112, pilot points 18X1-17X1, wire 168, (Fig. 8) commutator 278 and to plus battery.

The final step of the call sender is effected by this current and the call sender passes to normal position, permitting the talking bridge to be closed.

In case the calling line is a party line, its telephone is that of Fig. 16 instead of

Fig. 10. The differences are three: The ringer is from line wire to earth (Fig. 16) instead of from line wire to line wire (Fig. 10). The circle of pins 241 has two extra pins, 290 and its insulated companion between 254 and 248, the two extra pins providing one extra full step for the arm 242. The disk 250 is cut to open the switch 247 when arm 242 is upon either pin 290 or pin 243. 70

In case the calling line is a party line, its call sender (Fig. 16) has its arm 242 on sub-normal 253, and the arm 242 requires two full steps to advance it to its normal pin 243 to complete the talking bridge between the line wires. 80

At this time with 242 upon 253, the switch 247 is closed and the magnet 248 is connected from line wire 422 to earth.

The 44th circuit as traced above, now operates to charge the magnet 248, which by attracting its armature advances the arm 242 from pin 253 and by releasing its armature the arm 242 into engagement with pin 290; by the movement of the arm 242 and its attached disk 239, the notch of 250 is brought under the bell crank dog 249, and switch 247 is permitted to open. See Fig. 17.

The opening of the switch 247 removes the magnet 248 from line wire 422, and the closing of 242 and 290 connects the magnet 248 from earth to line wire 421, over path 248, 417, 411, 290, 242, 427.

A final step of the arm 242 now is required to advance it from pin 290 to pin 243. This, in the case of a party line is supplied over 45th circuit, the 45th circuit being ineffective in the case of such a telephone as that of Fig. 10.

The 45th circuit (charging call sender magnet over wire 421 after first ring) extends from earth or minus battery at the telephone (Fig. 10) through the call sender magnet 248, over line wire 421 of the A-line (Fig. 1) through the A-switch as adjusted, wire 113, (Fig. 2) pilot points 18X2-17X2, wire 169 (Fig. 3) commutator 279 and to plus battery.

The circuits operative while the pilot switch is in its No. 8 stop position will be found equally effective in a reverting call where the B-switch is connected with the line already seized by the A-switch, that is to say, when the called station is upon the same line as the calling station, and when the ringing currents of 43rd circuit pass over the same telephone line as the signal currents of 44th and 45th circuits.

When the first variation of the 43rd circuit is closed for ringing station 1, 2, 3, 4, 5, the ringing ground is placed upon line wire 422 and the ringing currents pass over line wire 421 and through the bells to earth before the arm 242 of the calling station is advanced from pin 253. When the 43rd cir- 125 130

cuit is closed, the ringing ground is placed upon line wire 421 and the ringing currents are sent over line wire 422 upon which at that time the call sender magnet 248 is connected, as well as the ringing bridges to earth. The first impulse of ringing current will charge the call sender magnet 248 which, by action of the call sender arm 242, as described, will be removed from line wire 422 and transferred to line wire 421, while the call sender continues to hold the talking bridge open. The call signals then will be rung upon the bells connected from line wire 422 to earth, and upon the conclusion

15 of the signals, 44th and 45th circuits will be closed. The 44th circuit will be ineffective since its functions have been accomplished by the first impulses over 43rd circuit. The 45th circuit then acts as described above.

20 By this means, the closing of the talking bridge of the calling station is delayed until after the first ring. In case the call is a reverting one, ringing back upon the calling line, the talking bridge of the calling telephone is not permitted to interfere with the ringing circuits or signals of the first ring.

The first ring having been accomplished, the pilot brushes leave their No. 8 stop position.

25 The 46th circuit (charging pilot clutch through No. 8 pilot stop position) extends from minus battery (Fig. 3) through commutator 277, wire 167, (Fig. 2), pilot points 17X14-18X14, wire 192, pilot clutch magnet 215 and to plus battery.

The pilot brushes stop in their No. 9 position on 19th and 20th sets of pilot points, in which position they await the removal of the receiver from the hook of either tele-

40 phone. This action will be described under the headings of "repetition" of "ring" and "release."

45 Referring to 36th circuit and assuming that the tested line had been found engaged, the first variation of the 36th circuit would have resulted in charging the relay 204 when the moving pilot brushes were upon their 12th and 13th sets of points, which is not a stop position, the signal controller brushes 50 being then at rest upon their 43rd set of points. By the charging of the relay 204, under busy test condition, the 37th circuit locks it.

55 Relay 204 being charged and locked, the pilot switch upon reaching its No. 6 stop position does not close 38th circuit to start the signal controller; the signal controller remains off-normal with its brushes on its 43rd set of points until after the pilot has passed 60 talking position. (See 65th circuit).

As the signal controller does not pass to its normal position at this time, 39th circuit to pass the pilot switch from No. 6 stop position cannot be closed. Instead, the pilot 65 is advanced by current over 47th circuit.

The 47th circuit (charging pilot clutch through No. 6 pilot stop position after test upon a busy line) extends from minus battery (Fig. 3) over right movable and front contact points of charged relay 204, wire 178 70 (Fig. 2), pilot point 13X12-13, wire 192, pilot clutch magnet 215 and to plus battery.

From the No. 7 stop position, 41st circuit advances the pilot switch into No. 8 stop position, 42nd, 44th and 45th circuits operate as described, and 46th circuit passes the pilot brushes to their No. 9 stop position, without completing 43rd circuit.

The 43rd circuit, in the case of a test upon a busy line, extends from the two terminals of the ringing generator through the wires 196 and 197, through the upper two levels of the ringing register, through wires 171 and 172, closed contact points of charged ringing relay 205, wires 437 and 438 to signal controller points 1X6 and 1X8, where the circuit is open because the signal controller brushes are off normal. At the same time, the tone circuit is closed to the calling subscriber.

90 The 48th circuit (busy tone) extends from the busy-tone transformer 209, (Fig. 3) over wire 193, (Fig. 2), pilot points 21X11-10, wire 185, (Fig. 4) signal controller points 43X7-8, wires 433 (Fig. 3) and 107', through condenser 256, to wires 101' and 101; also from the busy-tone transformer 209 over wire 194, pilot points 22X11-10, wire 184 (Fig. 4) controller points 43X5-6, wire 436 (Fig. 3) and 106', through condenser 255 to wires 103' and 103, from these points, 103 and 101, the two sides of the circuit may be traced over the 57th or talking circuit to the A-telephone.

95 In case the selected line is found busy by test, the signal controller brushes will remain upon their 43rd set of cylinder points while the pilot brushes are in their No. 7 stop position, closing a variation of the 41st circuit whereby the wait of the calling telephone user may be shortened.

100 The 41-1st circuit (charging the pilot clutch through No. 7 pilot stop position and controller off-normal points, before restoring the call sender to normal and after test upon a line busy by test) extends from minus battery (Fig. 3) through commutator 275, wire 165, 165', (Fig. 4), signal controller points 43X4-3, wire 181, (Fig. 2), ringing register points and brush, wire 198, pilot 115 points 15X14-16X14, wire 192, pilot clutch magnet 215 and to plus battery.

(4.) Repetition of ring.

120 The first ring is given with a minimum delay after the selected line is found free. To do this with a minimum delay, the ringing cycle is repeated as frequently as possible, since the first ring must await the beginning of the code cycle.

To repeat the ring at the frequency of recurrence of the code cycle as determined for the first ring would not be desirable. Therefore, I provide (paragraph G) fast commutators 271, 272, 273, 274, 275, 276, 277, 278, and 279 at a speed of about 20 revolutions per minute, for the first ring, as described. I provide also an auxiliary or slow commutator, 270, having a speed of one revolution for an integral number of revolutions of the fast commutators, and I provide it with but one segment of such an angular dimension that the time of closed circuit of commutator 270 equals or slightly exceeds the total time of the closures of commutator 275, and therefore includes the time of closure of commutators 271, 272, 273 and 274.

The commutators 275 and 270 being geared together at (say) a ratio of 6-to-1, 20 and being adjusted to begin their closures at the same time, the commutator 270 will remain closed continuously for one cycle of the effective periphery of commutator 275, then will remain open for five such cycles. 25 A circuit having these two commutators in series would receive the impulse determined by commutator 275 for one effective cycle, then would be held open by commutator 270, for the time of three complete cycles of commutator 275, when the action of the commutator 275 would be repeated. Such a circuit is the 51st circuit. With a commutator 275 at 20 revolutions per minute and 275 and 270 at 6-to-1, one complete code ring 35 would be given every eighteen seconds.

With a pilot switch in No. 9 stop position: 40 The A-station or calling telephone lifts the receiver from the hook and thereby closes 49th circuit. 45 The 49th circuit (current supply to A-line) extends from minus battery, (Fig. 3) left to right through helix of relay 202, wire 103, (Fig. 2) pilot points 20X1-19X1, wire 112, (Fig. 1), through A-switch as adjusted, wire 422 of the A-line, (Fig. 10) through the telephone bridge 246, 257, 258, 243, 242, 427, of the A-station, returning over line wire 421, (Fig. 1) through A-switch as adjusted, wire 113, (Fig. 2), pilot points 19X2-50 20X2, wire 101, (Fig. 3) and left to right through helix of relay 201 to plus battery. The relays 201 and 202 are charged, thereby closing 50th circuit for advancing the pilot switch.

55 The 50th circuit (charging pilot clutch through No. 9 stop position under control of A-line) extends from minus battery, (Fig. 2), pilot points 19X13-12, wire 179, (Fig. 3), left movable and front contact 60 points of charged relay 202, wires 519 and 178, (Fig. 2) pilot points 19X14-20X14, wire 192, pilot clutch magnet 215 and to plus battery.

65 The pilot brushes move to No. 10 stop position in engagement with the 21st and

22nd sets of pilot points, in which position the 51st circuit will ring upon the B-line periodically.

The 51st circuit (charging relay 205 for repeated ring) extends from minus battery (Fig. 3) through commutator 271, (or 272, 273, 274 or 275 as determined by the setting of the ringing register brushes) over wire 161, (Fig. 2) ringing register point, register brush, wire 173, (Fig. 3) right to left through helix of relay 205, wire 108 (Fig. 2) pilot points 10X9-11X9, (closed by the auxiliary brushes normally upon pilot points 34X9-35X9), wire 120, (Fig. 3), commutator 270 and to plus battery.

The periodic ringing continues as long as the pilot switch remains in No. 10 stop position.

(5.) Conversation and release.

It is desirable that the connection be under the control of either telephone (paragraph H) for the purposes of disruption of the connection and release of the lines.

Release of the lines and restoration of all operating apparatus to normal condition of disuse, awaiting further service, becomes automatic when the pilot switch reaches its No. 13 stop position. The pilot leaves its No. 9 position, its No. 10 position, its No. 11 position and its No. 12 position under control of the telephones of the connected lines, and it is desirable that either telephone be able to control the pilot and therefore to effect the discontinuance of the connection, in any of the pilot stop positions No. 9, No. 10, No. 11, or No. 12.

In the improved system of my invention, either substation telephone may advance the pilot switch from any one of the four stop positions named, and therefore either telephone may advance the pilot from all of them, from its first telephone control stop position, No. 9, to its position of total automatic release, No. 13.

This is effected by attaining the following conditions of control:

In pilot stop position No. 9: The lifting of either telephone switch hook will advance the pilot to its stop position No. 10 or 11.

In pilot stop position No. 10 or No. 11: Either of these stop positions may be held only by maintaining one sole telephone off the hook, the other remaining on the hook. The A-telephone off the hook holds the pilot in No. 10 stop position, the B-telephone off the hook holds the pilot in No. 11 stop position. By raising the remaining switchhook, the pilot switch is advanced to No. 12 stop position; by depressing the switchhook previously lifted, the pilot switch is advanced to No. 13 stop position. If both the telephones are lifted simultaneously when the pilot switch is in stop position No. 9, the pilot moves continuously from No. 9 to No. 12.

In pilot stop position No. 12: This stop position may be held only by keeping both telephones off the hooks. The hanging up of either or both will advance the pilot switch 5 to its No. 13 or automatic-restoration stop position. Hence, if the pilot has been advanced from No. 10 stop to No. 12 stop by hanging up the telephone originally lifted when in No. 9 stop position, the pilot will 10 move continuously from No. 10 to No. 13 stop position.

In the four stop positions, Nos. 9, 10, 11 and 12 the telephone lines are connected through to their controlling relays 201, 202, 15 203, 204. It is by means of these relays and circuits and apparatus associated with their armatures, that the desired control features are attained. See Fig. 11 for simplified circuits.

20 While ringing periodically upon the B-line, the A-telephone is in readiness for conversation, and awaits the response of the B-telephone.

When the B-station lifts the receiver from 25 the hook, the 52nd circuit is closed through that station, charging relays 203 and 204 and by the 53rd circuit advancing the pilot switch to No. 12 or talking position.

The 52nd circuit (current supply to B-line) extends from minus battery (Fig. 3) left to right through helix of relay 204, wire 518, left back and movable points of discharged relay 205, wire 438, (Fig. 4), signal controller points 1X6-5, wire 153 (Fig. 2) 35 pilot points 22X4-21X4, wire 144, (Fig. 5) interconnector switch adjusted, wire 442, (Fig. 6) B-switch as adjusted, line wire 422 of B-line, speech transmitting bridge of B-station, returning over line wire 421 of B-line, through B-switch as adjusted, wire 441, 40 interconnector switch as adjusted, wire 148, pilot points 22X5-21X5, wire 155, signal controller points 1X7-8, wire 438, right movable and back contact points of discharged 45 relay 205, wire 521, left to right through helix of relay 203, wire 175, pilot points 22X9-21X9, and to plus battery.

Relay 204 charged by 52nd circuit, closes 53rd circuit.

50 The 53rd circuit (charging pilot clutch through No. 10 pilot stop position upon response of B-station) extends from minus battery (Fig. 3) over right movable and front contact points of charged relay 204, wire 178, pilot points 21X14-22X14 wire 192, pilot clutch magnet 215, and to plus battery.

The 54th circuit becomes operative at this time, but will be discussed under the title of "Special Services, Meters".

60 When the pilot brushes reach their No. 11 stop position with the A-telephone and B-telephone both off the hook, 55th circuit is closed to advance the pilot brushes from the No. 11 stop position without stopping.

65 The 55th circuit (charging pilot clutch

through No. 11 stop position with both telephone hooks up) extends from minus battery (Fig. 3) over right movable and front contact points of charged relay 204, wire 519, front and movable contacts of charged 70 relay 202, wire 179, (Fig. 2), pilot points 23X12-13, wire 192, pilot clutch magnet 215 and to plus battery.

When the pilot brushes reach their No. 12 stop position, in engagement with the 25th 75 and 26th sets of pilot points, the 56th or talking circuit is formed.

The 56th circuit (talking) extends from the A-telephone over line wire 421, through the A-switch as adjusted, wire 113, pilot 80 points 25X2-26X2, wire 101, (Fig. 3) wire 101, condenser 256 on the plus side of the circuit, wires 107 and 107, right back and movable contact point of discharged ringing relay 205, wire 438 (Fig. 4), signal controller points 1X8-7, wire 155, (Fig. 2), pilot points 25X5-26X5, wire 148, (Fig. 5) interconnector switch as adjusted, wire 441, (Fig. 6), B-switch as adjusted, line wire 441 of the B-line to the B-telephone; also from the A-telephone over line wire 422, through the A-switch as adjusted, wire 112, pilot points 25X1-26X1, wires 103 and 103', through the condenser 255 on the minus side, wires 106, left back and movable contact 95 points of discharged ringing relay 205, wire 437, signal controller points 1X6-5, wire 153, pilot points 26X-25X4, wire 144, interconnector switch as adjusted, wire 442, B-switch as adjusted, line wire 422 of the 100 B-line, to the B-telephone.

Current supply for the transmitters is over 49th and 52nd circuits traced through the No. 12 pilot stop position.

After the close of the conversation, if the 105 A-telephone hook lever be depressed, 48th circuit will be broken, relays 201 and 202 will be discharged and 57th circuit will be formed, charging the pilot clutch to pass the brushes from the No. 12 stop position to the 110 No. 13 stop position, which is a position of automatic release and restoration.

The 57th circuit (charging pilot clutch through No. 12 stop position under control of A-station) extends from minus battery 115 (Fig. 2) over wire 109, pilot points 25X13-12, wire 179, (Fig. 3) left movable and back contact points of discharged relay 202, wires 523 and 105, (Fig. 2) pilot points 25X14-26X14, wire 192, pilot clutch 120 magnet 215, and to plus battery.

The following variations may occur in the signal circuits in the No. 9, No. 10, No. 11 and No. 12 pilot stop positions:

If, after conversation, with the pilot 125 brushes in the No. 12 stop position, the B-telephone hook lever is depressed before that of the A-telephone, the following circuit is formed:

The 57-1st circuit (charging pilot clutch 130

through No. 12 stop position under control of B-station) extends from minus battery (Fig. 3) over right movable and back contact points of discharged relay 204, wire 105, (Fig. 2) pilot points 25X14-26X14, wire 192 pilot clutch magnet 215, and to plus battery.

With the pilot switch in No. 9 stop position, the connective division awaits the lifting of either receiver from its hook, the pilot advancing under control of either of the two connected telephones. If the A-telephone lift the receiver, 49th circuit is closed, closing in turn 50th circuit and advancing 15 the pilot switch under control of the A-line, as described. If the B-telephone lift the receiver, 52nd circuit is closed for current supply to the B-line, tracing the circuit through No. 9 pilot stop position instead of 20 No. 10 pilot stop position, and charging relays 203 and 204, in turn closing 58th circuit.

The 58th circuit (charging pilot clutch through No. 9 stop position under control of B-line) extends from minus battery (Fig. 3) 25 over right movable and front contact points of charged relay 204, wire 178, (Fig. 2) pilot points 19X14-20X14, wire 192, pilot clutch magnet 215, and to plus battery.

The pilot brushes leave their No. 9 stop 30 position and upon reaching No. 10 stop position find 58th circuit again closed, through pilot points 21X14-22X14, instead of 19X14-20X14, so that the brushes continue their movement and stop in No. 11 stop 35 position, where the pilot switch awaits either the lifting of the A-telephone to complete the connection or the restoration of the B-telephone to the hook, to release the connection.

40 If the A-telephone be lifted at this time, with the pilot brushes at rest in No. 11 stop position, 55th circuit will be completed and the brushes will move to No. 12 stop, or talking position.

45 If, with the brushes at rest in the No. 11 stop position, the B-telephone be restored to its hook, 59th circuit will be formed, advancing the brushes from that position.

The 59th circuit (charging pilot clutch 50 through No. 11 stop position with both telephone hooks down) extends from minus battery (Fig. 3) over right movable and back contact points of discharged relay 204 to wire 523 extending thence over wire 105, 55 (Fig. 2) pilot points 25X14-26X14, wire 192, pilot clutch magnet 205, and to plus battery.

The circuits described above, namely, 58th and 59th, together with circuits previously 60 described, provide for the release of a connection from any pilot waiting position by the B-line without the coöperation of the A-line.

With the pilot brushes at rest in the No. 65 10 stop position, the A-line is awaiting the

response of the B-line and the B-line is being rung upon. The action following the response of the B-line has been described. If the A-line restore the receiver to the hook, either by reason of receiving the busy tone or by reason of a decision that the B-line "does not answer" or for any reason, relays 201 and 202 are discharged and 60th circuit is formed to move the pilot brushes from the No. 10 position.

The 60th circuit (charging pilot clutch through No. 10 stop position under control of A-line) extends from minus battery (Fig. 3) over right movable and back contact points of uncharged relay 204, wire 523, back and movable contact points of discharged relay 202, wire 179, (Fig. 2) pilot points 21X12-13, wire 192, pilot clutch magnet 215 and to plus battery.

When the brushes reach No. 11 stop position, 59th circuit is closed and when the brushes reach No. 12 stop position 57th circuit is closed, passing the brushes to No. 13 stop position, which is a releasing position.

(6.) Restoration.

The pilot brushes, upon reaching No. 13 stop position, close 61st and 62nd circuits simultaneously to charge the clutches of A-switch and B-switch for the restoration of those switches to normal. The time limit for the closing of these circuits is fixed by a predetermined angle of rotation of the A-switch and after the lapse of that time limit, the A-switch closes 63rd circuit to advance the pilot switch to its No. 14 stop position. The A-switch further determines the time of closing 66th circuit to advance the pilot to normal. Thus in the restoration of the connective division to normal, the A-switch is utilized as auxiliary to the pilot switch, it having finished all necessary functions as an A-switch.

The 61st circuit (charging B-switch clutch for restoration) extends from minus battery (Fig. 2) over wire 109, pilot points 29X13-12, wire 141, (Fig. 5), through interconnector switch as adjusted, wire 444, through closed off-normal trunk test points 237 of the B-switch, wire 514, B-clutch magnet 238, and to plus battery.

The 62nd circuit (charging A-switch clutch for restoration) extends from minus battery (Fig. 1) over A-switch points 39X2-3 in the case of calling line No. 714, wire 145, (Fig. 2), pilot points 28X10-11, wire 186, (Fig. 1), A-clutch magnet 216, and to plus battery. This circuit is broken as soon as the A-switch brushes in 3rd quadrant of the cylinder leave the 44th points; that is, as soon as all directory-number notches of the A-clutch disk have passed the clutch dog. The A-switch brushes stop thirty points off normal, on the 31st, 42nd and 20th sets of cylinder points.

105

110

115

120

125

130

- The 63rd circuit (charging pilot clutch through No. 13 stop position under control of A-switch) extends from minus battery (Fig. 1) over A-cylinder points 42X2-31X2, wire 110, (Fig. 2) pilot points 28X14-29X14, wire 192, pilot clutch magnet 215, and to plus battery.
- The time interval between the closing of the 62nd and 63rd circuits is sufficient to permit the secondary connector clutch to move its disk until the last notch has passed the clutch dog, after which time the cylinder brushes can stop only in normal position. Upon the closing of 63rd circuit, the 15 pilot brushes move, break 61st and 63rd circuits and stop in No. 14 pilot stop position, closing 64th circuit, for restoring the interconnector and also 65th circuit for restoring the signal controller, in case the latter switch is off-normal. The pilot also closes 67th circuit to restore the A-switch from 31st set of points, and the A-switch in turn upon reaching normal closes 66th circuit to restore the pilot to normal.
- The 64th circuit (charging interconnector clutch for restoration) extends from minus battery (Fig. 2) over wire 109, pilot points 31X13-12, wire 143, (Fig. 5) interconnector clutch magnet 219 and to plus battery.
- The 65th circuit (charging signal controller clutch magnet for restoration if off normal) extends from minus battery (Fig. 2) over wire 109, pilot points 30X13-12, wire 133, (Fig. 4) signal controller points 43X11-12, wire 506, signal controller clutch magnet 213, and to plus battery.
- The 67th circuit (charging A-switch clutch for restoration from 31st set of points) extends from minus battery (Fig. 1) over A-switch points 42X2-31X2, wire 110, (Fig. 2), pilot points 30X10-11, wire 186 (Fig. 1) A-clutch magnet 216, and to plus battery. This circuit is broken as soon as the A-switch brushes move.
- The 66th circuit (charging pilot clutch through No. 14 stop position for restoration to normal) extends from minus battery (Fig. 1) over cylinder points 1X2-12X2, wire 111, (Fig. 2) pilot points 30X14-31X14, wire 192, pilot clutch magnet 215, and to plus battery.
- This completes the restoration to normal of all the switches used in connection, the register of each cylinder being restored by the return of the cylinder to normal and the ringing register being restored by the return of the pilot brushes to normal.
- (7.) *Lamp signals.*
- Associated with the switches of each connective division is a system of lamp circuits controlling three lamps 261, 262 and 263, having caps respectively red, white and green. These lamps, by their glowing and the order of their appearance and disappearance, afford an index to the condition of the division (paragraph K).
- The red lamp 261 and the white lamp 262, are connected directly to the contact bank of the pilot switch, and, by their respective illuminations, indicate the position in which the pilot switch is at rest from time to time. The green lamp is connected to contact points of a timing device or slow relay and the glowing of the green lamp 263 indicates that the pilot switch has remained in some one of its positions or groups of positions throughout a period of time which may be designated as a time limit. This time limit is not the same for all of the positions of the pilot switch.
- The timing device (paragraph M) comprises a ratchet disk 281 and two magnets with pawls, magnet 282 for driving the disk 281 against its spring 283, and magnet 284 for releasing the disk for restoration. The ratchet disk 281 carries a stud 285 which operates after a sufficient number of driving impulses, to close a pair of contact springs 286-287 to illuminate the green lamp 263, and upon a subsequent driving impulse, to close a second pair of contact springs 288-289 connected to the pilot clutch magnet 215 and to minus battery.
- The length of time required after starting from its normal position and before closing its alarm and clutch contact points (paragraph N) is measured by the same number of impulses or ratchet teeth at all times (an adjustment being provided initially to determine the number of impulses required) and the total time period is regulated by the frequency of the driving impulses. Commutators traveling at different speeds provide impulses of different frequencies, providing variant time limits from the same timing device.
- Assuming that the ratchet disk 281 is adjusted to close its alarm points after the 4th impulse, impulses may be furnished at the rate of one in each 3 seconds during the process of setting up a connection, and if the setting up of the connection is not completed within 12 seconds, the alarm contacts 286-287 will be closed and the green lamp 263 will glow for 3 seconds. During conversation, impulses may be furnished at the rate of one in each 3 minutes and should any conversation endure longer than 24 minutes, the alarm contacts 286-287 will be closed, and the green lamp 263 will glow for six minutes to call the attention of the attendant.
- The second pair of timer contact points 288-289 are associated with the pilot clutch and are included in 68th circuits.
- The red-lamp circuit extends from plus battery (Fig. 3) through the red lamp 261,

wire 159, (Fig. 2) pilot points on 7th level, wire 127, (Fig. 8) wire 420 and to minus battery.

The red-lamp circuit (paragraph Q) closed initially in No. 2 position on points 35X7-36X7, is continued by the point-and-brush combinations, 4X7-37X7, 6X7-39X7, 8X7-41X7, 42X7-43X7, 43X7-44X7, 12X7-1X7, until the main pair of brushes stop in position No. 6, the auxiliary pair at that time resting upon points 2X7 and 3X7.

The red-lamp circuit is closed again when the pilot brushes leave No. 6 stop position, over points 4X7-15X7, 6X7-17X7, 8X7-19X7, until the pilot brushes leave No. 9 stop position.

The red-lamp circuit is not closed in No. 10 stop position (repeated ring), in No. 12 stop position (talking), nor in No. 1 stop position (normal).

The red-lamp circuit is closed in No. 11 stop position over pilot points 12X7-23X7.

The red lamp circuit is closed after leaving talking position over pilot points 16X7-25X7, 15X7, 28X7-17X7, 30X7-19X7, 32X7-21X7, 33X4-34X4 and wire 139 to minus battery, 35X4-34X4 and wire 139, 36X7, 36X7-27X7, 38X4-37X4 and wire 139, 28X7-39X7, 30X7-41X7, 32X7-43X7, 44X7-1X7.

The white-lamp circuit extends from plus battery (Fig. 3) through the white lamp 262, wire 154, (Fig. 2) pilot points 22X7-21X7 when pilot brushes are in No. 10 stop position, wire 127, (Fig. 8) wire 420, and to minus battery. The circuit is repeated over pilot points 24X7-23X7 when pilot brushes are in No. 11 stop position.

The green-lamp circuit extends from plus battery (Fig. 3) through the green lamp 263, wire 540, contact points 287-286 of the timer, wire 447, alarm relay 259, wire 448, through lamp-and-release switch 264 and to minus battery.

The 68th circuit (pilot release by timer) extends from plus battery (Fig. 2) through pilot clutch magnet 215, wire 157, (Fig. 3) timer springs 288-289 when closed, wire 449, lamp-and-release switch 264 when closed and to minus battery.

The lamp-and-release switch (paragraph P) 264 has but two positions; in one of which it opens the green-lamp circuit and in the other of which it opens the 68th circuit, but it is unable to open both circuits at the same time. Hence the lamp-and-release switch controls both circuits to render one of them always effective; to disable one of them but not both of them at the same time. The lamps are unnecessary when the exchange is unattended, but at such a time the 68th is desirable. The switch 264 renders automatic the substitution of the one for the other.

When it is desired to have both the green

lamp circuit and the 68th circuit operative 65 at the same time, the green-lamp circuit is closed by switch 264 and the 68th circuit is closed by switch 265. In this case, when the timer is on the fast drive the green lamp will glow 3 seconds and the division then 70 will release if it has not received attention, and when the timer is on the slow drive the green lamp will glow 6 minutes and the division then will release if it has not received attention. 75

If it is desired to have the glowing of the green lamp accompanied by an audible signal, the alarm switch 260 may be closed.

The release circuit may be made to close before the alarm circuit if desired by including in 80 68th circuit timer points 286-287 in lieu of 288-289, and by including in the green lamp circuit timer points 288-289 in lieu of 286-287.

The interpretation of the lamp signals is 85 as follows:

With the red lamp glowing alone, its connective division is actively engaged in setting up a connection or in restoring the switches 90 after disruption of a connection.

With a white lamp glowing alone, the A-telephone is off the hook and the B-telephone is being rung periodically.

With a green lamp glowing alone, the 95 connective division has been in No. 12 stop position (talking position) for the time limit.

With all lamps dark, the connective division is in the talking position within time limit, or is idle and normal.

With red and green lamps glowing at the 100 same time, their pilot switch is in one of its transient stop positions and has been longer than the time limit in setting up or restoring its switches.

With the red and white lamps glowing at 105 the same time (paragraph Q) the B-telephone is off the hook, and the A-telephone is not off the hook, indicating that the called party has answered the call and the calling party either has abandoned it or is negligent in lifting his receiver. The pilot brushes are standing in No. 11 stop position. By this special signal I am able to produce independent signals from the A-line and B-line, yet avoid the cost of a B-line lamp, 110 combining the red off-normal lamp with the white A-line lamp as a substitute. 115

With all three lamps burning at the same time, the condition which holds the pilot brushes in No. 11 stop position will have 120 endured long enough to reach the time limit.

The red lamp burns in all transient positions except No. 6 and No. 10 stops and is dark for a brief interval while the pilot 125 brushes pass No. 6 stop position. No. 6 stop is a position immediately following the test upon the selected line. If the selected line

is found idle by test, then when the pilot brushes reach No. 6 stop position, relay 204 will be uncharged, and will not be charged immediately by relay 204 but relay 204 instead through its contact points will charge the signal controller clutch over 38th circuit, and the pilot brushes must rest in No. 6 stop position until the controller brushes move from 43rd set of points to their first 10 set of points, at which time 40th circuit will be closed to advance the pilot brushes further. By this pause of the pilot brushes in No. 6 stop position, the interval of darkness of the red lamp will be so extended as 15 to be decidedly noticeable.

If, however, (paragraph K) the selected line is found busy by test, then the locking relay 204 will be charged during all the 20 time that the pilot switch is in its No. 6 stop position, and the following circuit will be closed.

The 69th circuit (red-lamp busy-test circuit killing red-lamp wink) extends from plus battery (Fig. 3) through the red lamp 25 261, wire 159, (Fig. 2) pilot points 13X5-14X5, wire 178, (Fig. 3) right front and movable contact points of locked relay 204 and to minus battery. Current over this path keeps the red lamp glowing at the time 30 when it is normally dark in pilot No. 6 stop position, and produces a variation in sequence, rather than by a distinct signal, so that an observing attendant may be advised that the selected line was found busy by test.

35 The normal sequence of lamp operations is red, dark, red, white, dark, red. The indications are red while setting the selective switches, dark while awaiting the signal controller movement after busy test 40 upon an idle line, red during the first ring, and while awaiting the lifting of one of the telephone receivers, white during the periodic ring, dark during conversation, red during restoration. A short white flash is 45 given during restoration as the auxiliary brushes pass pilot points 22X7 and 24X7. This flash is meaningless and is neglected.

Upon a call engaging a busy line, the sequence of lamp operation is red, white, red. 50 The indications are red continuously until the No. 10 pilot stop position is reached, white while the calling subscriber has his receiver off the hook in the repeated-ring position, during which time he will hear the busy tone, and immediately red upon the restoration of the calling telephone to its hook, there being no long dark period for conversation.

Upon a "don't answer" call in which the 60 selected line is engaged and rung, but does not respond to the call, the sequence of lamp operations is red, dark, red, white, red. The indication by the dark interval between the first two red intervals is that the line was 65 found idle. In this case, some indication of

the calling subscriber's action may be learned from the operation of the white lamp. If the white lamp is kept glowing for many seconds, the A-line is awaiting the response of the B-line, but if the white lamp flashes 70 very briefly, then the A-line has abandoned the call without awaiting the response of the B-line as would be the case of a test call in which the user of the A-telephone merely 75 desired to test the telephone or to exhibit its operation to a visitor, or in which no connection or conversation was desired.

In a reverting call, the sequence of lamp operations is red, dark, red, dark, red. In a reverting call the B-line and A-line being 80 the same, relays 201, 202, 203 and 204, all will be charged simultaneously when a telephone is taken off the hook. For this reason the pilot brushes will not stop in the No. 10 or periodic ringing position and the white 85 lamp will receive but a transient flash.

(8) Normaling.

The automatic normaling of an abnormal connective division is attained by two independent means which become operative to normal the division under various conditions of abnormality.

(First): The timer circuit (68th) will advance the pilot switch and ultimately normal the entire division in event of delayed control from the usual source of control.

(Second): The primary connector or A-switch by returning to normal or by stopping upon its 31st set of points also 95 will advance the pilot switch from certain 100 pilot positions of rest and ultimately will normal the entire division in case the primary connector should return to normal 105 prematurely. These means are additional to restoration by subscriber's control from conditions or positions not abnormal.

A system of mutual circuits exists between the pilot switch and the A-switch. In pilot position No. 2 the A-switch is set 110 off-normal, and the pilot switch will advance without co-operation of the A-switch into pilot stop position No. 9. However, if the A-switch has not stopped upon a selective position, that is, with its brush 267 115 upon a point in the first quadrant, then it will have stopped with that brush upon point 31X2 by the time the pilot switch reaches its No. 8 stop position, and a normaling circuit (70th) will be closed to advance the A-switch to its normal position.

The 70th circuit (normalizing A-switch from pilot No. 8 stop position) extends from minus battery (Fig. 1) cylinder points 125 42X2-31X2, wire 110, (Fig. 2) pilot points 17X10-11, wire 186, (Fig. 1) A-switch clutch magnet 216 and to plus battery. The A-switch brushes advance from 31st set of points and interrupt 70th circuit, the brushes then stopping in normal position.

The pilot brushes having advanced without the A-switch co-operation and having stopped in No. 9 pilot stop position, the pilot clutch magnet 215 is placed under control of either relay 202 or relay 204 or both. If a B-line has been selected, relay 204 may be under control of a telephone upon the selected line, but relay 202 cannot be at this time under control of a telephone upon a telephone line because the A-switch brushes are at normal.

The control of relay 202 by any telephone circuit being impossible under the abnormal conditions assumed, its control is transferred to a purely local circuit within the connective division (71st circuit) and by the action resulting, the pilot of the division is set forward to result in ultimate normalizing.

20 The 71st circuit (advancing pilot from No. 9 stop position by normal A-switch) extends from minus battery (Fig. 3) through helix of relay 202, wire 103 (Fig. 2) pilot points 20X1-19X1 wire 112, (Fig. 1), A-switch cylinder points 34X3-2, wire 158 (Fig. 2) pilot points 19X11-10, wire 188 (Fig. 3) resistance 211 and to plus battery. This circuit charges relay 202 over a local circuit in lieu of a telephone line circuit, the substitution being made because of the irregular action of the A-switch.

By the organization of the relay 202 and the operation of its armatures, the 50th circuit is closed, advancing the pilot brushes 35 from No. 9 stop position as though controlled by an artificial A-line. As the pilot brushes leave No. 9 stop position, they break the 71st circuit, discharging relay 202 and when they reach No. 10 pilot stop position, they close 40 60th circuit as though the telephone had been hung up upon the artificial line which advanced the pilot switch from No. 9 stop position. In No. 11 stop position the pilot brushes close 59th circuit and in No. 12 pilot 45 stop position they close 57th circuit, advancing them farther to No. 13 stop position which is an automatic release position.

In No. 13 stop position the pilot brushes start the B-switch for restoration over 50 61st circuit and start the A-switch upon a second revolution by charging its clutch over 72nd circuit.

The 72nd circuit (charging A-switch clutch with A-switch normal and pilot in 55 stop No. 13) extends from minus battery (Fig. 1), cylinder points 1X2-12X2, wire 111 (Fig. 2), pilot points 28X13-12, wire 186 (Fig. 1), A-switch clutch magnet 216 and to plus battery.

60 The A-switch clutch is held charged through the first quadrant by 62nd circuit and the brushes reach the 31st set of points closing the 63rd circuit after which 64th, 65th, 66th and 67th circuits are closed as 65 described for usual release and restoration.

When the pilot switch is in normal position, the 73rd, 74th and 75th circuits are closed within the pilot switch for restoring the A-switch from any stop position other than normal and for restoring the signal controller from its sole off-normal stop position upon its 43rd set of points.

The 73rd circuit (charging A-switch clutch through selective position and normal pilot) extends from minus battery 75 (Fig. 1) points in second and third levels of 4th quadrant of A-switch, wire 145 (Fig. 2) pilot points 1X10-11, wire 186, (Fig. 1) clutch 216 of primary connector and to plus battery.

The 74th circuit (charging A-switch clutch through sub-normal position and normal pilot) extends from minus battery (Fig. 1) cylinder points 42X2-31X2, wire 110; (Fig. 2) pilot points 2X10-11, wire 186 85 (Fig. 1) primary connector clutch magnet 216 and to plus battery.

The 75th circuit (charging signal transmitter clutch through sub-normal position and normal pilot) extends from minus battery (Fig. 2) pilot points 2X13-12 wire 133 (Fig. 4) cylinder points 43X11-12 wire 506, signal controller clutch magnet 213 and to plus battery.

The normalizing circuit of the timer (68th 95 circuit) has the task of normalizing the entire division when a predetermined time limit has expired.

Where a timer, such as I have described (paragraph M)-is used in connection with 100 a connective division such as I have described, a single timer may be made to serve all the switches of a division by associating it with the pilot switch.

In so using the timing device, I divide the 105 action of the pilot switch into three parts. First, the setting up of the connection, including all action up to the lifting of one of the receivers from the telephone hook; second, the period of conversation, being 110 measured from the lifting of a receiver upon its hook; third, the period of release and restoration of the switches of the division. The first period occupies a small fraction of a minute; the second period may have a 115 second limit by the service agreement existing between the subscribers and the telephone company or it may have an arbitrary limit for a reasonable maximum telephone conversation, say ten, twenty or thirty minutes; the third period will require but a small fraction of a minute. To give the same time limit or the same timer adjustment to all three of these periods would not meet fully the requirements of an automatic 120 telephone exchange.

I meet the requirements of such a connective division with a single timing device by providing a single timing device (paragraph SD.) with two sources of driving power 130

adapted to drive the device at different speeds. By this means I am able to drive the device rapidly for the first and third periods and slowly for the second period.

6 In connection with an impulse driven timing device a pilot switch and two sources of impulses of different speeds, I provide a circuit (76th) for the driving magnet of the timing device which passes through the pilot switch to the first impulse device in all stop positions of the pilot switch in which the connection is being set up, I provide a break in the driving circuit between the stop positions of the pilot switch for setting up the connection and the stop positions for conversation, I provide a circuit (77th) from the driving magnet of the timer to the glow impulse device in all stop positions. I provide an interruption in the driving circuit between the pilot stop positions classified as conversation stop positions and the pilot stop positions for release of the divisions. I provide a circuit (76th) from the driving magnet of the timer to the source of fast impulse through pilot stop positions for release of the division. I provide an interruption for the driving circuit between the last stop position for release and the normal stop position of the pilot switch. I also leave the driving circuit open when the pilot switch is normal. In each of the three interruptions of the driving circuit provided as above described, I provide a release circuit (78th) through the pilot switch while in motion and operating to release and restore the timing device.

10 The second pair of timer points also restore the timer itself, since by them the pilot is driven until the pilot releases the timer to open the second pair of points.

14 It is obvious that the release may be mechanical between the moving parts of the pilot switch and the timer if so desired.

The 76th circuit (timer fast drive) extends from minus battery (Fig. 3) through commutator 277, wire 167, (Fig. 2) pilot points 3X8-4X8, wire 152 (Fig. 3) timer driving magnet 282 and to plus battery. This circuit is closed over successive pilot points until the pilot brushes leave No. 9 stop position. It is closed again in No. 13 and No. 14 stop positions.

18 The 77th circuit (timer slow drive) extends from minus battery (Fig. 3) through commutator 269, revolving slowly, over wire 125 (Fig. 2) pilot points 22X8-21X8, wire 152 (Fig. 3) timer drive magnet 282 and to plus battery. This circuit is closed over successive pilot points in stop positions 10, 11 and 12. In all of these positions at least one telephone receiver must be off the hook to prevent the pilot switch from going to an automatic release position.

22 The 78th circuit (timer release by pilot) extends from minus battery (Fig. 2) pilot

points 20X3-21X3 which are closed by brushes in motion between No. 9 and No. 10 stop position but which are not closed in either stop position, wire 151 (Fig. 3) timer release magnet 284 and to plus battery.

26 This circuit is closed as above after the setting up of the connection and upon the removal of either telephone receiver from the hook, at which time the timer is released and restored to start from its normal position for its long period upon the slow drive. After conversation the timer is restored by a similar circuit over pilot points 27X3-28X3; and after restoration of the switches, as the pilot switch leaves No. 14 stop position, the timer is restored again through 78th circuit over points 20X3-21X3, these points being closed in this instance by the auxiliary brushes.

30 The use of a timer upon a connective division insures the proper operation within reasonable limits both of the connective division and of the telephone users served by the division at any time. I extend this principle in my improved automatic telephone exchange (paragraph SE) by associating a similar timer with the division starter. The timer associated with the division starter insures the proper operation within reasonable limits, both of the division starter itself and of the division being started.

35 The timer of the division starter is shown in Fig. 9. It has three circuits, 79th, 80th, and 81st.

40 The 79th circuit (drive circuit for starter timer) extends from minus battery (Fig. 3) through commutator 276, wire 446 440, (Fig. 9), starter point 3X8 and through the starter brushes to point 3X7, while the starter brushes are in their sub-normal stop position to close 4th circuit, thence over wire 461 to drive magnet 280 of the starter timer.

45 The 80th circuit (release circuit for starter timer) extends from minus battery (Fig. 9) wire 418, starter cylinder points 4X7-8, wire 460, timer release magnet 221 and to plus battery. This circuit is closed transiently while the starter brushes are in motion from sub-normal position of starting the division to the next normal position of waiting for a subsequent call. At this time, the starter timer is restored to its normal position of idleness.

50 The 81st circuit (release of starter by timer) extends from minus battery upon contact points 222 of starter timer and when the timer has closed its contacts, it extends to contact point 223, and over wires 462 and 501, to and through clutch magnet 218 and wires 503 and 424 and to plus battery.

55 The starter timer may be adjusted to a very short period of time, say 5 or 10 seconds, and if a division is not operated to the No. 3 pilot stop position within that time limit, then the timer will set the starter

brushes forward, which in turn will restore the timer and the time limit will be repeated as the starter comes to rest in sub-normal position to start the next idle switching division.

- 5 An "out of service" condition of the division starter (paragraph SF) is desirable when all divisions are busy, that the starter may not rotate needlessly. To prevent this 10 needless rotation, I provide an "out of service" stop notch in the starter clutch disk which stops the brushes upon the No. 41 set of points. The only circuit involved is the 82nd circuit which is closed by any normal pilot switch of the section, and which, when closed, passes the starter brushes from the No. 41 set of points.

The 82nd circuit (division starter "out of service" circuit) extends from minus battery (Fig. 2) wire 109 pilot points 1X18- of any pilot switch of the section, wire 126, (Fig. 9) starter cylinder magnet 218, wires 503 and 424 and to plus battery.

This circuit is normally closed and renders 25 the starter operative. When the 82nd circuit is opened, it renders the division starter inoperative or "out of service."

(9.) *Special services.*

30 *Rotational selection.*

The circuits of the rotational selection system (paragraph SG) are shown in Fig. 12 in which are shown parts of several connective divisions. The cylinder brush 224-1 is 35 the brush bearing the same label in Fig. 5 upon cylinder point 34X10. The wire 444 is the wire 444 of Figs. 5 and 6. As this wire is intermediate between 441-1 and 444-3 it 40 might properly bear a label 444-2, being the wire 444 of the 2nd secondary connector.

The cylinder brush 224-1 is a part of the 45 interconnector of the 1st connective division and represents the complete connective division as shown in Figs. 1, 2, 4, 5 and parts of Fig. 3. The cylinder brush 224-2 is a 50 similar brush in the 2nd connective division and represents a complete similar division. The dotted lines extending to the left above 55 the brush 224-2 indicate the existence of still other similar connective divisions, related to the 1st and 2nd divisions as those divisions are to each other, namely by embracing terminals of the multiplied test wires 444-1 to 444-7 inclusive. In connection with the brush 224-1 is shown a row of eleven cylinder contact points, being those cylinder contact points in 11th level of 4th quadrant of Fig. 5, points 34X11 to 44X11 inclusive, and 60 connected to the test wires of the successive trunks of a group of trunks extending to a group of secondary connectors. Similar points are shown for the brush 224-2 and similar points exist in analogous connective 65 divisions.

Of the trunks extending from the interconnectors to the secondary connectors, only the test wires 444 and similar, are shown in Fig. 12, only those wires being involved directly in the rotational test circuits.

The secondary connector of Fig. 6 is the 70 2nd of the group and its parts appear in Fig. 12 as follows: Cylinder magnet 238, off-normal switch 237, connecting conductor 75 514, trunk conductor 444 for test and clutch control. These parts which are involved in the rotational test system, as applied to the specific machine telephone apparatus disclosed in this application, serve to indicate the complete secondary connector of Fig. 6. 80 They are duplicated at 238-1, etc., to represent the complete 1st secondary connector of the set and they are further duplicated at 238-3, 238-4, and 238-5 to indicate still other complete secondary connectors.

In addition, and specifically for the purpose of the rotational test, three relays 206-1, 206-2, 206-3 are provided for the 1st, 2nd and 3rd secondary connectors respectively.

The relays 206-1, 206-2 have each two armatures of which the right armature has a back contact spring which follows the armature substantially until the front contact spring is engaged, thus affording energization for the helix through the armature and back contact for sufficient length of time to enable the relay to lock electromagnetically over a circuit through its back and front contacts. The relay 206-3 is a simple relay breaking its armature circuit when its core 100 is charged. The relays 206-1 and 206-2 are of high resistance and adapted to carry current from the main battery 200 continually or for long periods. The specific operation of these apparatus parts is that the act 105 which charges the clutch magnet 238-1 shall charge also the relay 206-1 (83rd circuit) which relay will lock (84th circuit) and produce and maintain a false busy test or guard circuit (85th circuit) upon the test conductor 110 444-1 associated with that secondary connector, so that the next succeeding call will pass that secondary connector as being engaged whether the secondary connector actually is engaged or not. While the secondary connector is engaged in fact, the 23rd- 115 2nd circuit or fact-busy circuit will exist in addition to the 85th or false-busy circuit. After the removal of the fact-busy by reason of the restoration of the secondary connector 120 to normal, the false busy will continue by reason of the locked relay 206-1.

Upon the promotion of the next call into this set of secondary connectors, whether from the 1st division having brush 224-1, 125 from the second division having brush 224-2, or from any other division, the wire 444-1 will give a busy test to the 23rd circuit, and the interconnector will search further and take the secondary connector, having tested 130

over wire 444, and having found that wire open both at the off-normal switch 237 and at the left armature of the relay 206-2. Upon operating the decimal register of the 5 secondary connector, the switch 237 closes, and upon operating the clutch 238 (34th circuit) the relay 206-2 is charged (83rd circuit) and locks (84th circuit) producing a false guard (85th circuit) upon the guard

10 wire 444. This false guard continues regardless of the continuance or discontinuance of the fact guard upon the wire.

Upon the receipt of the next succeeding call into the group of secondary connectors, 15 the searching interconnector will find busy by test both the wire 444-1 and the wire 444 and will search further for a wire idle by test, engaging and accepting the wire 444-3. Upon the operation of the register, the 20 switch 237-3 will be closed and upon the operation of the clutch 238-3 over the wire 444-3, the control relay 206-3 will be charged over 86th circuit. By the charging of the 25 relay 206-3, relays 206-2 and 206-1 will be released, removing the false busy from the test conductors 444 and 444-1.

The conductor 444-2 never carries a false test. It is the control conductor of the group and the last conductor of the rotational group.

The object of dividing the total trunks into two groups (paragraph SH) of which the first group is rotational and the second group ordinal, is found when a plurality of 35 calls are received very closely following each other. If all trunks are rotational and all but the control trunk are busy by false busy and two calls are received, the second call may have passed all trunks idle in fact before the first call will have removed the false busy from those trunks. Thus, the second call would be defeated and would not select a trunk although trunks were idle in fact at time. With the two groups rotational 40 and ordinal, the ordinal group will care for all calls passing through the rotational group in busy hours, while the rotational group will effectually provide for rotational selection upon any specific repeated call during the idle hours. It is particularly for 45 the repeated call and particularly for the repeated call during the idle hours that my improved system of rotational selection is designated.

50 The relay 206-3 does not involve the high current carrying requirements of relay 206-2 or 206-1, and the relay 206-3 may be sufficiently sensitive to respond to the testing currents over 23-2nd circuit as well as to 55 currents over 34th and 61st circuits. By this adjustment, even though the third secondary or control unit be busy, relay 206-3 will be charged to relieve the false busy from the other units of the rotational group.

60 The 83rd circuit (charging rotational re-

lay No. 6) follows 23rd circuit as far as wire 444, then extends farther through off-normal switch 237, wire 463 (Fig. 12) right back and movable contact points of relay 206-2, helix of relay 206-2, wire 464, interdivisional wire 465, closed points of relay 206-3 and to plus battery.

The 84th circuit (locking rotational relay No. 6) extends from minus battery (Fig. 12) over right front and movable contacts of charged relay 206-2 through helix of relay 206-2, wire 464, interdivisional wire 465, closed points of relay 206-3 and to plus battery.

The 85th circuit (false guard for rotational test) extends over 23rd circuit as far as wire 444, thence (Fig. 12) over wire 466 through left closed points of charged relay 206-2, wire 467, wire 463, wire 514, helix of clutch magnet 238 and to plus battery.

The 86th circuit (charging rotational control relay) extends over 23rd, 34th or 61st circuit as far as wire 444-3, thence through closed off-normal switch 237-3, wire 468, helix of relay 206-3 and to plus battery.

Service meter.

The meter circuit (54th circuit) is controlled over pilot points 23X10-11 and 24X10-11 in cooperation with the left armature of relay 203. The pilot points are closed by the two pairs of brushes bridged vertically while the pilot switch is in its No. 11 stop position.

It will be noted that the pilot switch seldom stops upon this position since it is a stop position used only in an irregular call where the user of the A-line telephone has neglected to lift the receiver promptly upon making his call. In the ordinary operation of the pilot switch, the A-line receiver being lifted before the B-line receiver is lifted, the pilot switch moves continuously from No. 10 stop position to No. 11 stop position; thus the 54th circuit is closed only transiently as the pilot brushes pass from the No. 10 stop, the position of repeated ring, or of A-line waiting for B-line to respond, to the No. 11 stop, the position of conversation, the circuit not being closed in either of the two positions mentioned. The circuit also is subject to control of the relay 203.

The 54th circuit (charging meter) extends from plus battery (Fig. 3) through left contact points of relay 203 if charged, wire 170 (Fig. 2) pilot points 23X11-10, wire 114 (Fig. 1) through the A-switch as adjusted, wire 423 (Fig. 7) wire 445, helix of meter 225 and to minus battery.

The 15th circuit is not interrupted to form the 54th circuit, and the 54th circuit being formed as a shunt around the resistance 211 of the 15th circuit. The current of the 15th circuit is not sufficient to operate the meter 225 because of the resistance 211.

When the B-line telephone is lifted from the hook, current is taken over 52nd circuit, charging relays 203 and 204. Relay 204 advances the pilot switch as described and relay 203 charged by the B-line and in cooperation with the pilot switch operates the meter of the A-line over 54th circuit.

Free line service.

- 10 When it is desired to receive calls upon a designated line as a B-line, without causing the actuation of a meter upon any calling or A-line to such a connection, a circuit is used (87th circuit) by which the relay 204 is charged and the relay 203 remains uncharged for an interval sufficient to advance the pilot brushes from stop position No. 12. This being effected, the relay 204 advances the pilot switch but the relay 203 does not coöperate 75 with the pilot switch to close the 54th circuit. After the pilot switch has attained its No. 12 stop position for conversation, the relay 203 may be charged by 52nd circuit.
- 25 The charging of the relay 204 without 80 charging the relay 203, is effected by applying upon the B-line a source of current, from the plus terminal of the main battery or equivalent, from which source current will flow through relay 204 to minus battery.
- 30 This source may be a contact applied either transiently or permanently, and applied either to the line conductor directly or to the sub-station telephone equipment and thence to the line conductor. In Fig. 13 the 85 free-service source of current is applied to the line conductor. In Fig. 14 it is shown as applied through a jack contact upon a manual switchboard. In Fig. 15 it is shown as applied through the sub-station telephone.
- 40 The 87th circuit (free-line circuit to avoid operating meter) extends from plus battery (Fig. 13) through an inductance 226 to conductor 422 (the relay 14' being charged over 45 15th circuit at this time) from which point the circuit may be traced (Fig. 7) to the secondary connector (Fig. 6) where it joins 52nd circuit and continues through B-switch as adjusted, wire 442 (Fig. 5) through inter- 50 connector switch as adjusted, wire 144, (Fig. 2) pilot points 21X4-22X4, wire 153 (Fig. 4) signal controller points 1X5-6, wire 437 (Fig. 3) left points of discharged relay 205, wire 518, helix of relay 204 and to minus battery. This charges relay 204 without 55 charging relay 203.
- 60 Assuming that line 714 extends to a manual switchboard, a variation of the 87th circuit may be traced from plus battery (Fig. 65 14) through closed contact of idle manual switchboard jack 227 over wire 422 and to Fig. 7, the cut-off relay 14' of Fig. 7 being charged by 15th circuit at this time. From this point, the circuit may be traced as for 87th circuit traced above.

The free meter circuit of Fig. 13 is possible where the subscriber's line is long or where a source of current is not available at his telephone. Its disadvantage is that the inductance leg 226 remains upon the talking conductor during conversation. 70

Where a source of current is available at the telephone, another variation of the 87th circuit may be traced from plus battery (Fig. 15) through added spring 228 of the hook switch 246 prior to the answering of the telephone user, thence over wire 422 to Fig. 7 (the cut-off relay 14' being charged over 15th circuit at this time) and thence as before over 87th circuit as traced above. 75

In each of these variations, the auxiliary source of current is removed from the line when the call is answered. When a plug is inserted in jack 227, the 52nd circuit will be formed through the operator's switching equipment and will charge the relay 203. When the receiver is lifted in Fig. 15, the auxiliary source of current will be removed from the wire 422 and 52nd circuit will be formed. 80

Supra-busy system.

To enable the toll operator to seize a busy line, disregarding its guard (paragraph SP), a circuit (88th) exists from the signal transmitter controller clutch to the toll board whenever the busy tone is returned over a toll trunk. The means for effecting this is to use as toll trunks all trunks having the units figure "2", thereby appropriating a 95 definite position of the primary connector or A-switch cylinder brushes exclusively for toll trunks manual-to-automatic; and then wiring a circuit through this appropriated A-switch cylinder position and through the signal controller sub-normal or 43rd set of points to the signal controller clutch. Over this circuit the signal controller may be advanced to normal. 100

The 88th circuit (supra-busy) extends 110 from minus battery upon the manual switchboard, through manual key 229, (Fig. 1), wire 469, to cylinder point 4X2 on all A-switches of the section upon which the toll-to-automatic trunks terminate. When the A-switch is in that predetermined selective position which it assumes in response to a call initiated upon a toll-to-automatic trunk, then the brush 267 will rest upon the point 4X2 and the connected brush 268 will rest upon the point 15X2. By these brushes thus adjusted by a call over any manual-to-automatic trunk, 88th circuit will be continued from wire 469, through A-switch points 4X2-15X2, wire 117, (Fig. 2), pilot points 22X12-13, wire 133, (Fig. 4), signal controller points 43X11-12, wire 506, controller clutch magnet 213 and to plus battery. 115

The busy tone being heard by the toll op- 120 125 130

erator, the manual key 229 may be closed, thus closing the 88th circuit and advancing the signal controller to normal, removing the manual-to-automatic trunk conductors 5 from the source of tone current and connecting them to the conductors of the selected busy line.

Party-line telephone.

- 10 Fig. 16 shows the circuits of the party-line telephone (paragraph SQ). A difference is found in the wire 470 and its accompanying pin 290 with the incidental additional tooth in the ratchet. The disk 239 has its notch cut of sufficient width to permit the dog of 249 to enter the notch in two positions of the arm 422, namely, when the arm 422 is upon pin 290 or upon pin 243. 15 When the arm is in any position other than upon pin 290 or 243, the circuit of magnet 248 is closed from ground through off-normal switch 247 to line conductor 422. When the arm 422 is upon the point 290, the 20 switch 247 is open and the magnet 248 is connected instead from the ground through conductor 470, pin 290, arm 422 and thence to line conductor 421. By this means, the magnet 248 is transferred from line 422 to 25 line 421 while code ringing currents are sent over line 422.

30 Referring to Fig. 17, an interference device is disclosed, (paragraph SR) in connection with the party-line telephone whose circuits are shown in Fig. 16. The telephone system herein shown and described as a whole may be operated without this interference device, but the convenience of the system for telephone users is increased by 35 the interference feature.

35 The shaft 280 carries sleeved upon it the spur gear 286. The spur gear 286 carries the pin 283 and the ratchet carries the pin 281. The two pins 281 and 283 are connected by the spiral spring 282. Thus the wheel 286 may be turned independently of the ratchet and may be operated upon to increase the spring tension upon the ratchet. The spur gear 287 is carried upon the crank 40 shaft 288 and meshes the spur gear 286. The spur gear 287 carries rigidly attached to it the cam 289, the cam 291 and the pin 292. It is restrained by the pawl 293 against the action of the spring 282. The pawl 293 45 when lifted by the cam 291 closes the electrical switch 294. The slide bar 295 when lifted by the pin 292 acts through pin 284 to lift and operate the armature of the magnet 248 and permits thus a step of the 50 ratchet, the preliminary mechanical step hereinbefore referred to in the initiation of a call, the pin 292 engages the inclined cam face of the slide bar 295 just prior to the completion of one crank revolution, thus effecting the first step of the ratchet as the

final act of turning the handle to initiate a call.

The cam 289 receives the tooth 285 of the cam arm of 249 when the dog of the arm 249 is out of the notch of the disk 239. When 70 the dog of 249 is in the notch of 239, the tooth 285 is withdrawn from the path of the tooth of cam 289. Thus, if the disk 239 is normal, the armed member 249, by withdrawal of its tooth 285, unlocks the spur gear 287.

The brush 242 being normal, and spur gear 287 being unlocked, the crank may be turned one complete revolution, but no more, since when the revolution is nearly completed the pin 292 operates the slide bar 295, which, through the pin 284, operates the armature 301, and permits a step of the ratchet, which moves the disk 239, which in turn moves armed member 249 and moves 80 tooth 285 which in turn moves armed member 249 and moves tooth 285 into the path of the tooth of cam 289, thus stopping the spur gear 287 at the end of one complete revolution. The pawl 293 prevents return 90 movement of the spur gear 287. The sending of the call follows as described in the early portions of this specification.

95 My improvement comprises the addition of the contacts or electrical switch 294 upon pawl 293, cam 291 upon the spur gear 287, the magnet 296 and its armature 297 which carries the interference tooth 298. The cam 291 is attached to the side of the spur gear 287 and does not interfere with the meshing 100 of gears 286 and 287. The pawl 293 is of wide tooth and overlangs the side of the spur gear 287 so that it is engaged by the cam 291 and lifted from the spur gear teeth transiently by that cam.

105 The operation of my interference device is as follows:

Upon beginning to turn the crank 299 and thereby turning the spur gears 287 and 286, the cam 291 raises the pawl 293 and closes 110 the switch 294. If this results in the energization of the magnet 296, then that magnet will attract its armature 297 and draw its interference tooth 298 into the spur gear teeth, stopping the further progress of the 115 call. Upon the release of the crank handle by the telephone user, the spring 282 will return the spur gears to normal position, since the pawl 293 is ineffective because of the cam 291. By this return, the circuit of magnet 296 is opened. If, however, at the time of turning the crank 299 the magnet 296 is 120 not charged, the call may progress in the usual manner.

To effect the proper operation of the magnet 296 at the proper time and at no other times, I connect the two sides of the line 422 and 421 together through the contacts of the cut-off relay 14' at the central office when the line is not in use. I then connect the 130

two conductors 491 and 492 to the two line conductors 421 and 422 respectively. When the line is idle, the two line conductors are at the same potential, being connected to the same terminal of the main battery 200, and no current flows through 296 when 294 is closed. When the line is in use, the two sides of the line are of different potentials since they are connected to the two terminals of the main battery through relays 201 and 202 if the line is calling, and relays 203 and 204 if the line is called; then when the switch 294 is closed, current will flow through the magnet 296, interrupting the further progress of the crank 299 as described.

15 I have described my invention as applying to a specific type of automatic telephone exchange and I have described specific applications of the principles of my invention when used in connection with the specific exchange. I do not desire to be misinterpreted in view of such limited description, since my invention is not limited to the specific forms and applications here shown, and 20 many modifications may be made in the apparatus and details of application to an exchange without departing from the spirit or scope of my invention.

Having thus described my invention, what 25 I claim as new, and desire to secure by Letters Patent, is:

1. In an automatic telephone system, a group of lines divided into smaller groups; a plurality of connective divisions serving 30 all of said lines; a division starter; a line relay for each of said lines, said line relays being grouped in association with said smaller groups of lines; an auxiliary relay for each such group of line relays; means whereby 35 an auxiliary relay will be charged whenever a line relay is charged; and further means whereby a charged auxiliary relay will cause the operation of said division starter.

40 2. In an automatic telephone system, a group of lines divided into smaller groups, a group of relays for each such smaller group of lines and containing one relay to each line; an auxiliary relay for each such group of relays, said auxiliary relays determining 45 the order in which said line relays may be charged when effort is made to charge at the same time two or more line relays located in different relay groups.

50 3. In an automatic telephone system, a group of lines divided into smaller groups; a group of relays for each such smaller group of lines and containing one relay to each line; and means for determining the 55 order of operation of two of said line relays located in different groups when effort is made to operate them at the same time.

4. In an automatic telephone system, a plurality of groups of line relays; an auxiliary relay for each group and a circuit from

a source of current through contact points of the auxiliary relay of a first group to the line relays of another group and a branch path from said circuit through contact points of the auxiliary relay of said second group to the line relays of a third group.

5. In an automatic telephone system, a plurality of groups of line relays; an auxiliary relay for each group and a circuit from a source of current through contact points of the auxiliary relay of a first group to the line relays of another group and a branch path from a point between said auxiliary relay and the line relays of said second group and extending through contact points of the auxiliary relay of said second group and thence to auxiliary and line relays of still other groups.

6. In an automatic telephone system, a plurality of relays, a sequence switch and a cirenit passing to said relays serially and through said sequence switch, said switch adapted to change the serial order of said relays upon said circuit.

7. In an automatic telephone system, a plurality of relays, a sequence switch, and a circuit passing to said relays serially and through said sequence switch, said switch adapted to change the serial order of said relays upon said circuit and means whereby 95 said relays control said sequence switch to cause said switch to operate to change the serial order of said relays upon said circuit, substantially as described.

8. In an automatic telephone system, a plurality of relays, a sequence switch and a circuit passing to said relays serially and through said sequence switch, said switch adapted to change the serial order of said relays upon said circuit, operating means 100 for said sequence switch, and a circuit controlling said operating means and controlled by the contacts of said relays.

9. In an automatic telephone system, a plurality of relays; a sequence switch having several positions, and a circuit passing to said relays serially and passing through said sequence switch a plurality of times, at least once at a point on the circuit between the said serially arranged relays, said circuit 110 passing to said relays in different serial orders of the relays when said switch occupies different positions.

10. In an automatic telephone system, a plurality of relays, a sequence switch and a circuit passing to said relays serially and passing through said sequence switch twice, or more times, at least once at a point on the circuit between the said serially arranged relays.

11. In an automatic telephone system, a plurality of line relays, a sequence circuit running to said relays in sequence and means for changing automatically the sequence order of the relays upon said sequence circuit.

12. In an automatic telephone system, a plurality of line relays; a sequence circuit running to said relays in sequence and means for changing automatically the sequence order of the relays upon said sequence circuit, said means controlled by said relays.
13. In an automatic telephone system, a plurality of line relays; a source of current; a sequence circuit from said source to said relays in sequence whereby an order of precedence among said relays is determined, and means for transposing portions of said sequence circuit whereby the order of said relays is varied.
14. In an automatic telephone system, a group of lines divided into smaller groups; a group of relays for each such smaller group of lines and containing one relay to each line; an auxiliary relay of each such group of relays, said auxiliary relays determining the order in which said line relays may be charged when effort is made to charge at the same time two or more line relays located in different relay groups, and a sequence switch, determining and from time to time varying the order of operation of two of said line relays located in different groups when effort is made to operate them at the same time.
15. In an automatic telephone system, a plurality of groups of line relays; an auxiliary relay for each group; a circuit from a source of current through contact points of the auxiliary relay of a first group to the line relays of another group; and a sequence switch changing the order of groups to render each group a first group at times.
16. In an automatic telephone system, a plurality of line relays; a plurality of auxiliary relays; a source of current; a series circuit from said source of current through said auxiliary relays to a point beyond the last auxiliary relay, closed when all said auxiliary relays are discharged; branches from said series circuit and extending to groups of said line relays; and a sequence switch changing the order of said branches upon said circuit when considered serially as engaged by tracing said circuit from said source.
17. In an automatic telephone system, a plurality of groups of line relays; an auxiliary relay for each group; a sequence circuit through said auxiliary relays in a serial order whereby relays in different groups are prevented from becoming charged contemporaneously, and a sequence switch varying the order of the auxiliary relays.
18. In an automatic telephone system, a plurality of groups of line relays, said groups arranged in a serial order, a plurality of connective devices for serving said lines and a single circuit-changing and device-selecting switch, controlling the identity of the connective device responding to any call and changing the serial order of said groups.
19. In an automatic telephone system, telephone lines; a plurality of groups of line relays; an auxiliary relay for each group, a sequence circuit through said auxiliary relays serially in order whereby relays in different groups are prevented from becoming charged contemporaneously; connective devices for serving said lines; and a starter for assigning a connective device to respond to a calling line, said starter also changing the serial order of said relays upon said circuit.
20. In an automatic telephone system, telephone lines; a plurality of groups of line relays; a sequence circuit for preventing line relays in different groups from becoming energized simultaneously; a sequence switch for varying the relation of the diverse groups with reference to said sequence circuit; a plurality of connective divisions and a starter for said divisions, said starter and said sequence switch being combined into a single circuit-changing switch having but one driving means.
21. In an automatic telephone system, a main battery; two terminal taps and a median tap for said battery, an operating circuit carrying at times current from said terminal taps, a test contact associated with said operating circuit and charged at times with the potential of one of said terminal taps and at times with the potential of the other of said terminal taps; and a test device connected to said median tap and operative when connected also to said test contact when said test contact is connected to either of said terminal taps.
22. In an automatic telephone system, a main battery; two terminal taps and a median tap for said battery, an operating circuit carrying at times current from said terminal taps, a test contact associated with said operating circuit and charged at times with the potential of one of said terminal taps and at times with the potential of the other said terminal taps and a test device connected to said median tap and operative when connected also to said test contact when said test contact is connected to either of said terminal taps; and means for isolating said test contact from both of said terminal taps, whereby said test device may not be operated when applied between said median tap and said test contact.
23. In an automatic telephone system, a main battery; an operating circuit; a test contact associated with said operating circuit and connected with either end terminal of said main battery dependent upon operating conditions of said circuit; and a test circuit extending from said test contact to a source of potential different from either end terminal of said main battery.

24. In an automatic telephone system, three terminals for supplying current and having three variant potentials constantly impressed thereupon; suitable sources of current for supplying said three potentials; a test wire connected at times with the first of said terminals and at other times with the second of said terminals; and a testing circuit extending at all times from the third 10 of said terminals and when active in test extending to either said first or said second terminal and being operative from said third terminal to either said first or second terminal.
25. In an automatic telephone system, a switch; a conductor leading thereto and normally open at said switch when said switch is normal; a magnet; means in said switch for closing the conductor through the 20 helix of said magnet to a first potential when said switch is off-normal; testing contacts connected with said conductor; means for applying a second potential to said test contacts for operating said magnet; a source 25 of electric current for supplying said potentials; test means for determining the busy or idle condition of said switch, extending from said conductor and operative by current either from said first potential through said 30 magnet and over said conductor or from said second potential upon the test terminals.
26. In an automatic telephone system, an electrical switching apparatus; an electric source furnishing two potentials, said apparatus being operative when connected between said two potentials; a test conductor isolated from said potentials when said apparatus is normal; a conductor conveying a 35 third potential median in value between said two potentials; and a testing device responsive to current from said median potential to either of said other potentials.
27. In an automatic telephone system, a 40 trunk circuit comprising in part a conductor normally isolated when the said trunk is in a condition of idleness and in a condition of readiness for use; means associated with said trunk for connecting said trunk 45 conductor to either of two terminals of a source of current; said source and its two terminals; a third terminal having a potential differing from the potential of either of the two terminals of said source whereby 50 current will flow from said third terminal over a conductor connected from said third terminal to either of the two terminals of said current; and a test circuit extending from said third terminal to either of the 55 two terminals of said source.
28. In an automatic telephone system, a 60 trunk; a trunk conductor forming a part of said trunk; operating mechanism associated with said trunk; a source of electric current; a circuit over said conductor and through said operating mechanism to one terminal of said source of current; means for applying the second terminal of said source of current directly to said conductor for operating said mechanism; means for isolating said conductor from both terminals of said source of current, said isolating means operative when said trunk is idle, and either or both of said connections to said source of current being effected continuously when said trunk is busy; a third terminal associated with said source of current intermediately of the said two terminals, whereby current will flow from said third terminal to either of said two terminals, and a test circuit extending from said third terminal to said conductor.
29. In an automatic telephone system, a trunk, the conductor of said trunk normally isolated from operating potentials when the 65 trunk is idle; means for applying a given potential to said conductor when said trunk is busy; further means for applying a second and different potential to said conductor at times when trunk is busy; and a 70 busy test circuit operative when connected to said conductor and when said conductor is connected to either of said potentials and inoperative when said conductor is isolated.
30. In an automatic telephone system, 75 three terminals having three variant potentials; a trunk having a conductor normally isolated from said three terminals; means for connecting said conductor to either of two said terminals when said trunk is busy 80 and a test circuit extending from said third terminal to said conductor.
31. In an automatic telephone system, an operating circuit having a test contact, which test contact bears variant potentials 85 as determined by the operating conditions and by the currents flowing over said operating circuit; means for isolating said test contact from said potentials when said circuit is idle, and a test circuit extending from 90 said test contact to a source of current variant from the ordinary potentials of said test contact.
32. In an automatic telephone system; an 95 idle selective switch in normal position; a 100 circuit; means for setting said switch off-normal, said means comprising a part of said circuit; other similar but off-normal switches; a searching switch having a clutch with electrical contact points; a testing relay; said circuit passing serially through points of said relay and points of said clutch; and circuits and apparatus such that said circuit is open either at said relay or said clutch when said searching switch is 105 moving and when one of said "similar but off-normal switches" is engaged by said searching switch, but is closed both at said

relay and at said clutch when said idle switch is engaged by said searching switch, whereby said normal switch is set off-normal.

33. In an automatic telephone system; an idle selective switch in normal position; means for setting said switch off-normal, said means comprising a part of said circuit; other similar but off-normal switches; a searching switch having a clutch with 10 electrical contact points; a testing relay; said circuit passing serially through points of said relay and points of said clutch; and circuits and apparatus such that said clutch is open either at said relay or at said clutch 15 alternately when said searching switch is moving and when a plurality of said off-normal switches are being passed, in a search for said normal switch.

34. In an automatic telephone exchange, 20 a plurality of trunks; a test wire in each trunk; a battery having positive and negative terminals; a set of conductors; a searching interconnector connecting said set of conductors to said trunks in succession; mechanical means for moving said interconnector to connect said set of conductors to the next trunk in order; and electrical busy-test devices for continuing the movement of the interconnector to break the connection 30 of said set from a trunk whose test wire is connected to either terminal of said battery.

35. In an automatic telephone system, a set of suitable sources of electrical currents; three terminals for said sources and having 35 variant potentials; a plurality of secondary connectors; a test wire for each of said secondary connectors, and normally isolated from said terminals; an off-normal switch for each of said secondary connectors and 40 adapted to connect said test wire to one of said terminals, means for connecting said test conductor to another of said terminals; and a testing device connected to the third of said terminals and adapted to be connected to one of said test wires, also, whereby current may flow through said test device if the said test wire is connected to one of the first two of said terminals, but not if the test wire be isolated from them.

50 36. In an automatic telephone system, a means for testing a telephone line for busy or idle condition and the subsequent adjustment of automatic switches in accordance with the result of the test, including automatic switches; a locking relay for recording the result of a transient test, the relay being held locked for sufficient time for reliable operation of the said automatic switches; and circuits from the contact 55 points of said relay to said switches and controlling one or the other of said switches.

37. In an automatic telephone system, two automatic switches, a relay adapted to operate one or the other of said switches, a cir-

cuit transiently closed for charging said relay initially, a locking circuit for said relay, said locking circuit controlled by one of said switches.

38. In an automatic telephone system; lines; a pilot switch; a first circuit extending through said pilot switch from a selected line to a busy-test relay; said relay; a second circuit from said relay to the clutch of said pilot switch and closed when said relay is energized; and a third circuit through helix 75 and contacts of said relay and contacts of said pilot switch whereby upon energization of said relay over said first circuit said second circuit will be held closed by continuing the energization of said relay over 80 said third circuit, said third circuit being closed through said pilot switch in the pilot's transient position of test wherein said first circuit is closed and also in the subsequent pilot stop position.

85 39. In an automatic telephone system, a fast commutator; a slow commutator; a circuit through said two commutators in series; said commutators being so related that the fast commutator is disabled during a portion of the revolution of the slow commutator, and a telephone ringing circuit controlled by said commutators.

40. In an automatic telephone system, a fast commutator; a slow commutator; a circuit through said two commutators in series, said commutators being so related that the slow commutator will close said circuit during a single complete cycle of the fast commutator and during which cycle the complete closing of the circuit will be subject to control by said fast commutator solely, said slow commutator subsequently opening said circuit for a predetermined number of complete cycles of said fast commutator, and 105 a telephone ringing circuit controlled by said commutators.

41. In an automatic telephone system, a group of commutators each for producing groups of code impulses repeatedly; a signal circuit for said impulses and through a selected one of said commutators; an auxiliary commutator included also in said circuit and operating to suppress certain groups of impulses, and a telephone ringing 110 circuit controlled by said signal circuit.

42. In an automatic telephone system, a system of commutators for ringing in a code manner upon telephone lines; a pilot switch, having two ringing positions; and means associated with said pilot switch for causing it to remain in its first ringing position during only one cycle of said commutators.

43. In an automatic telephone system, a fast commutator; a slow commutator; said commutators being so related that the fast commutator is disabled during a portion of the revolution of the slow commutator, and

- a telephone ringing circuit controlled by said commutators.
44. In an automatic telephone system, a fast commutator; a slow commutator; a ringing relay; a circuit through said ringing relay and said two commutators in series, said commutators being so related that the slow commutator will close said circuit during a single complete cycle of the fast commutator and during which cycle the complete closing of the circuit will be subject to control by said fast commutator solely, said slow commutator subsequently opening said circuit for a predetermined number of complete cycles of said fast commutator; and another circuit for said ringing relay, through said fast commutator independently of said slow commutator.
45. In an automatic telephone system, a group of commutators each for producing groups of code impulses repeatedly; a ringing device; a circuit for said impulses through said ringing device and through a selected one of said commutators; an auxiliary commutator; and an automatic switch operating to close said circuit as described, and later to include also in said circuit the said auxiliary commutator to suppress certain groups of impulses, substantially as described.
46. In an automatic telephone system, a system of commutators for ringing in a code manner upon telephone lines; a pilot switch, having two ringing positions; means associated with said pilot switch for causing it to remain in its first ringing position during one cycle of said commutators.
47. In an automatic telephone system, a fast commutator; a slow commutator; a ringing apparatus; a pilot switch having stop positions; a circuit through said ringing apparatus and said two commutators in series, in a stop position of said pilot switch, said commutators being so related that the slow commutator will close said circuit during a single complete cycle of the fast commutator and during which cycle the complete closing of the circuit will be subject to control by said fast commutator solely, said slow commutator subsequently opening said circuit for a predetermined number of complete cycles of said fast commutator; and a circuit through said ringing apparatus and said fast commutator alone in another stop position of said pilot switch.
48. In an automatic telephone system, a system of commutators for ringing in a code manner upon telephone lines; a pilot switch having two ringing positions; and auxiliary commutators and circuits associated with said pilot switch for causing it to enter its first ringing position at the beginning of a cycle of said ringing commutators, and to leave its first ringing position at the end of one code-ringing cycle.
49. In an automatic telephone system, a plurality of automatic switches; a set of commutators comprising code ringing commutators and automatic-switch-controlling commutators, said two classes of commutators operative alternately.
50. A system for party line ringing in an automatic telephone exchange including a pilot switch, having a preliminary position awaiting the termination of a code ringing interval before switching the ringing current upon the called line, having a first ringing position in which the code ringing current is switched to the called line for one code ring, having a second ringing position in which the code ring is repeated at comparatively long intervals and having a talking position in which no ringing is possible.
51. In an automatic telephone system, a pilot switch having four positions of rest and means for maintaining it in one of its four positions according as both, either or neither of the two connected telephones is off the hook.
52. In an automatic telephone system, telephones; a pilot switch having four positions of rest; two relays; circuits for said relays for maintaining said switch in one of its four positions according as both, either or neither of said two relays is energized; and circuits from said two relays to two telephones, whereby said telephones may control said pilot switch.
53. In an automatic telephone system, two telephone lines, a set of switches for connecting said two telephone lines, one of said switches being a pilot; a stop position for the brushes of said pilot switch in which position ringing currents are placed upon the B-line; and another stop position for the brushes of said pilot switch, said first position being maintained by said switch when the A-line telephone is off the hook and the B-line telephone is on the hook and said second position being maintained when the B-line telephone is off the hook and the A-line telephone is on the hook.
54. In an automatic telephone system, a set of switches for connecting two telephone lines, one of said switches being a pilot; a position of rest for the brushes of said pilot switch in which position ringing currents are connected to the B-line; and another stop position for the brushes of said pilot switch, said first position being maintained by said switch when the A-line telephone is off the hook and the B-line telephone is on the hook and said second position being maintained when the B-line telephone is off the hook and the A-line telephone is on the hook; and an additional stop position in said pilot switch which is maintained by said switch when both of said telephones are off the hook.

55. In an automatic telephone system, a connective division of switching apparatus having a pilot switch which may stand in a plurality of stop positions; two lamps; circuits through one of said lamps through certain stop positions of said pilot switch whereby said lamp is caused to glow when said pilot switch occupies predetermined stop positions; similar circuits for said other lamp through other stop positions in said pilot switch and through one of the stop positions pertaining to said first mentioned lamp also.
56. In an automatic telephone exchange, a connective division of switching apparatus having a pilot switch; a first lamp; a second lamp; a circuit through said first lamp and through contact points closed by said pilot switch in a plurality of its positions; and a circuit through said second lamp and through contact points in said pilot switch and closed by said switch in other of its stop positions.
57. In an automatic telephone exchange, a connective division of switching apparatus having a pilot switch occupying successive stop positions; a signal lamp illuminated by said pilot switch in positions before and after a test position; and further means for illuminating said signal lamp when said pilot switch is in said test position.
58. In an automatic telephone system, a connective division of switching apparatus; means for testing a line to determine its busy or idle condition; other means for causing a signal lamp to glow before and after the operations of said test; and still further means for causing said lamp to glow during the operations of said test if the line be found busy, and not to glow during the operations of said test if the line be found idle.
59. In an automatic telephone exchange, a timer system comprising a timer device; a first means for driving said device at fast speed; a second means for driving said device at slow speed; connective switches at times under control of telephone users and at times under automatic control; and means within said switches for connecting said timer device to said first driving means when said switches are under automatic control and to said second driving means when said switches are under control of telephone users.
60. In an automatic telephone exchange, a timer device closing two contact points one after the other; an alarm circuit connected to one of said contact points and a switch release circuit connected to the other of said contact points.
61. In an automatic telephone exchange, a timer device closing two contact points, one after the other; an alarm circuit connected to one of said contact points and a switch release circuit connected to the other of said
- contact points; and means for disabling one or the other but not both of said circuits.
62. In an automatic switch, a plurality of contact points in a single line; a plurality of brushes engaging some of said contact points, said brushes connected in a plurality of groups, each group adapted to close an independent circuit through said points.
63. In an automatic switch, a pair of contact points; two pairs of movable brushes movable over said points and connecting said points twice on one cycle of operations of the switch.
64. In an automatic telephone switch, a plurality of contact points arranged in a single row; four connected brushes engaging four of said contact points and closing three circuits simultaneously through said contact points.
65. In an automatic switch, a plurality of fixed contact points in a single row; a plurality of brushes engaging with said contact points, said brushes connected together and different brushes engaging the same contact points in two different stop positions of the switch.
66. In an automatic telephone exchange, a connective division; a pilot switch in said division; an A-switch in said division for connecting the pilot switch to a telephone line; and a circuit through normal points of said A-switch to release said pilot switch for restoration to normal.
67. In an automatic telephone exchange, a connective division; a pilot switch controlling said connective division; a primary connector to associate said division with a line; and a circuit through normal points of said primary connector to cause said pilot to restore said entire division to normal.
68. In an automatic telephone system, a connective division; a pilot switch controlling said division; a primary switch in said division and having 100 positions of adjustment, said primary switch adapted to connect said division with a telephone line in each of 100 of its positions and adapted to cause the restoration of the entire division to normal when in its normal or remaining position.
69. In an automatic telephone system, two automatic switches; two clutches, one pertaining to each of said switches; two normalizing circuits each containing a clutch and off-normal points of the automatic switch to which it and its clutch pertain and normal points of the remaining automatic switch.
70. In an automatic telephone system, a selective switch; a pilot switch; a clutch for said selective switch; a clutch for said pilot switch; a normalizing circuit for said pilot switch and extending in series through said pilot clutch, off-normal points in said pilot switch and normal points in said selective switch; and a normalizing circuit for said se-

- fective switch extending in series through said selective clutch off-normal points in said selective switch and normal points in said pilot switch.
5. 71. In an automatic telephone system, two switches; normally closed points in each of said switches; off-normally closed points in each of said switches; normalizing means for each of said switches, the normalizing means 70 of each switch being operative when its own switch is off-normal and the other switch is normal.
72. In an automatic telephone system, two switches normalizing means for each; normal 15 and off-normal contact points in each switch; a normalizing circuit for each switch extending through off-normal points of the switch and through normal points of the other switch and operative to normalize the 20 off-normal switch.
73. In an automatic telephone system, a pilot switch; two associated switches having normal and off-normal stop positions; and normalizing circuits from said pilot to each 25 of said other switches, through the normal of said pilot and the off-normal of said other switches, for restoring said other switches when said pilot is normal.
74. In an automatic telephone system, a 30 pilot switch having a plurality of stop positions, said positions divided into three groups of adjacent positions; a timer; a drive circuit for said timer closed in each position of said groups; and a release circuit for said timer closed by said pilot switch in transit between groups of said positions.
75. In an automatic telephone system, a 35 pilot switch having a plurality of stop positions divided into groups of adjacent positions; a timer; two sources of power for said timer; circuits through said pilot switch connecting said timer to one or the other of said sources; a release circuit for said pilot switch and through said timer; and releasing circuits for said timer through said pilot switch and closed between said groups of stop positions.
76. In an automatic telephone system, a 40 pilot switch having a plurality of stop positions; a timer having driving and releasing means; circuits for controlling said driving means and closed through said pilot switch in certain stop positions; a circuit for advancing said pilot and closable by said timer; and circuits in said pilot switch and between stop positions for releasing said timer.
77. In an automatic telephone system, a 45 pilot switch having stop positions classed in groups of adjacent positions; a timer; a circuit through each stop position other than normal for driving said timer; and circuits between stop positions for releasing said timer.
78. In an automatic telephone system, telephone lines; suitable devices for connecting them; a timer for said connective devices and operating slowly during conversation 50 and more rapidly during the setting up and 55 disruption of a connection; and means for restoring said timer to normal after each of the three periods mentioned.
79. In an automatic telephone system, a pilot switch having a plurality of stop positions, said positions divided into three groups of adjacent positions; a timer; a drive circuit for said timer closed in each position of said groups; a release circuit for said pilot switch and closed by said timer 70 after a predetermined delay; and a release circuit for said timer closed by said pilot switch in transit between groups of said positions.
80. In an automatic telephone system, a 75 pilot switch having a plurality of stop positions divided into groups of adjacent positions; a timer; two sources of power for said timer; circuits through said pilot switch connecting said timer to one or the other of said sources; a release circuit for said pilot switch and through said timer; and releasing circuits for said timer through said pilot switch and closed between said groups of stop positions.
81. In an automatic telephone system, a 80 pilot switch having a plurality of stop positions; a timer having driving and releasing means; circuits for controlling said driving means and closed through said pilot switch in certain stop positions; a circuit for advancing said pilot and closable by said timer; and circuits in said pilot switch and between stop positions for releasing said timer.
82. In an automatic telephone system, a 85 pilot switch having stop positions; a timer; means for driving said timer while said pilot switch is in certain stop positions; means for restoring said timer operative at other times; and means for driving said pilot closable by 90 said timer.
83. In an automatic telephone system, a 95 pilot switch, the pilot switch having a group of stop positions; a timer; means for driving said timer and effective while said pilot switch occupies stop positions of said group; a circuit closed by said timer and operating to drive said pilot beyond all stop positions of said group; and further means for restoring said timer to normal.
84. In an automatic telephone system, a 100 pilot switch having stop positions classed in groups of adjacent positions; a timer; a circuit through each group of stop positions other than normal for driving said timer; 105 circuits between groups of stop positions for releasing said timer; and a circuit, closable by said timer, and including driving mechanism of the pilot and adapted to drive the pilot beyond the stop positions of any group.
85. In an automatic telephone system, connective divisions; a division starter, and a timing device limiting the interval within 110 which a connective division may respond to control of said starter.

86. In an automatic telephone system, connective devices; a connective-device starter having normal and sub-normal positions and adapted to start one of said devices when occupying a sub-normal position; and a timer limiting the interval during which such starter may remain in a sub-normal position.

87. In an automatic telephone system, connective divisions; a division starter, having a stop position corresponding to each of said connective divisions and having an additional stop position; and a circuit extending from said starter to all of said connective divisions whereby any of said connective divisions may cause said starter to pass said additional stop position.

88. In an automatic telephone system, connective devices; a starter common to said connective devices and having a position corresponding to each of said connective devices and having an additional position not corresponding to any specific connective device; means whereby said 25 starter may be caused to occupy said additional stop position when all of said connective devices are busy; and means whereby said starter may be moved from said additional stop position by any normal idle 30 connective device.

89. In an automatic telephone system, connective devices; a starter for said connective devices, said starter having a position corresponding to each connective device 35 and having also an out-of-service position; and is caus operative by a connective device in normal position for moving said starter from its out-of-service position.

90. In an automatic telephone system, a plurality of connective devices each having a normal position of idleness and other positions; a starter for assigning said devices to duty and operative by the initiation of a telephone call, said starter having operating 45 positions and an out-of-service position; and electric circuit and means associated therewith for moving said starter from its out-of-service position; said circuit being closed by any of said connective devices in 50 normal position of idleness and being open when none of said connective devices is in normal position of idleness.

91. In an automatic telephone system, connective divisions; a division starter, having an out-of-service stop position; and a circuit extending from said starter to all of said connective divisions whereby any of said connective divisions, if normal, may cause said starter to leave said out-of-service 60 ice stop position.

92. In a busy-test system for general application in telephone, a guard circuit, means for closing said circuit, by the act of seizing a trunk for service, said guard circuit 65 being self-maintaining and further means

for opening said circuit, said further means being independent of said means for closing said circuit.

93. In a busy-test system for general application in telephony; a group of trunks for rotational use, one of said trunks being distinguished as a control trunk; means for creating and continuing a busy-by-test condition upon the several trunks until all are busy-by-test or busy by fact except the control trunk; and means in connection with said control trunk for removing the busy-by-test condition from the remaining trunks not busy in fact.

94. In a busy-test system for general application in telephony, a group of trunks; means for causing a trunk to test busy when in use; and means for continuing said busy-test condition upon each trunk, until all trunks of the group test busy in fact or by 85 test; and means in connection with the last trunk made busy to release the several other trunks from the busy-test condition, if not busy in fact.

95. In a busy-test system for general application in telephony, a trunk; a locking relay associated therewith; a guard circuit associated therewith and closed by said relay when locked; means for locking said relay when said trunk is seized; and means for 95 unlocking said relay independent of the seizure or release of said trunk.

96. In a busy-test system for general application in telephony; a first trunk; a second trunk; means for placing a false busy 100 test condition upon said first trunk when said first trunk is seized for use; and means for discontinuing the false busy upon said first trunk when said second trunk is seized for use.

97. In a busy-test system for general application in telephony, a group of trunks; a locking relay for each but one; a busy-test circuit for each trunk, said trunk testing busy when said relay is locked; a circuit for locking said relay and effective to hold said relay locked after the termination of the period of use of the trunk; and a relay associated with the said one exceptional trunk for unlocking said other relays. 115

98. In a busy-test system for general application in telephony, a plurality of trunks; a locking relay for each for imposing a false busy-test condition upon the trunk and for continuing the false busy-test condition upon the trunk after its period of use; an additional trunk completing a group of trunks; and a relay associated with said last-mentioned trunk for unlocking all of said other relays.

99. In a busy-test system for general application in telephony, a plurality of trunks; a locking relay for imposing the busy test condition falsely upon said trunks after they have been released from use; a control 120

125

130

trunk; a relay associated with said control trunk for unlocking said first mentioned relays, said last mentioned relay being operative to release first mentioned relays whenever

5 ever said control trunk is tested for busy and independently of whether said control trunk is busy or idle at the time of test.

100. A busy-test system for general application in telephony, comprising a plurality of trunks divided into a first group and a second group; means for using the trunks of said first group in rotation; and means for using the trunks of said second group in order whenever all of the trunks of the first 15 group are busy by test.

101. In a busy-test system for general application in telephony, a group of trunks, divided into two smaller groups; a system of fact-busy and false-busy testing in one of 20 said groups whereby said trunks are used in rotation when not busy in fact; and a busy-test system upon the trunks of said second small group whereby said trunks are used in order when said first trunks have been 25 found busy by test.

102. In an automatic telephone system, a subscriber's telephone; an interference magnet at that telephone; means for connecting said interference magnet from wire to wire 30 of the line; and means at the central office for holding said wires at the same potential when not in use and at different potentials when in use.

103. In a telephone system, a plurality of 35 duplicated circuits; means for placing a busy-test condition upon said circuits; and further means common to all the said circuits for removing the busy-test condition.

104. In a telephone system, a plurality of 40 duplicated circuits; means for placing a busy-test condition independently upon said circuits separately; and further means common to all the said circuits for removing the busy-test condition simultaneously from all 45 of them.

105. In a telephone system, a plurality of trunk circuits, a busy-test conductor for each; means associated with each trunk circuit for establishing and maintaining a

busy-test condition upon its busy-test conductor; and further means common to all said trunk circuits for discontinuing said busy-test condition.

106. In a telephone system, a first trunk circuit; another trunk circuit similar to said 55 first trunk circuit; a busy-test conductor forming a part of said first trunk circuit; another busy-test conductor forming a part of said other trunk circuit; means associated with said first busy-test conductor for establishing and maintaining a busy-test condition upon said conductor, and means associated with said other busy-test conductor for removing the busy-test condition from said first busy-test conductor. 60

107. In a telephone system, a trunk circuit, a busy-test conductor forming a part of said trunk circuit; another busy-test conductor; means associated with said first busy-test conductor for establishing and 70 maintaining a busy-test condition upon said conductor, and means associated with said other busy-test conductor for removing the busy-test condition from said first busy-test conductor. 75

108. In a telephone system, a circuit to be guarded by a busy-test condition; a source of potential, connection to which will institute the busy-test condition upon the said circuit; a means for connecting said circuit 80 and said source, and a further means for connecting said circuit and said source, said two means being independently operable to connect said circuit contemporaneously through two paths to said source, and said 85 two means being independently operable to discontinue connections, whereby the busy-test condition may be maintained upon said circuit after the disconnection of one of said means. 90

Signed by me at Toronto, county of York, and Province of Ontario, Canada, in the presence of two witnesses, Sept. 26, 1912.

DAVID S. HULFISH.
